MACHINE FOR OPERATING ON SHOES

Sidney J. Finn, Beverly, Mass., assignor to United Shoe Machinery Corporation, Paterson, N. J., a corporation of New Jersey

Application May 26, 1934, Serial No. 727,744

127 Claims. (Cl. 12—7)

This invention relates to machines for operating on shoes, and is herein illustrated as embodied in a machine having means for lasting a portion of a shoe and means for thereafter applying pressure and heat to the margin of the upper lasted inwardly over the shoe bottom and secured adhesively in lasted position. More particularly, the machine herein shown as an illustrative embodiment of the invention is constructed for operation upon a shoe the toe-end portion and the waist or shank portion of which have already been lasted, and is provided with means for lasting the shoe from the toe portion rearwardly as far as the previously lasted waist or shank portion and with pressing or ironing means for thereafter subjecting the margin of the upper throughout the length of the forepart to pressure and heat. It is to be understood, however, that the invention is not limited to a machine which operates upon, or is confined to operation upon, that particular portion of a shoe; and in various novel aspects, moreover, it is not limited to an organization which includes both lasting means and pressing or ironing means.

In the manufacture of shoes it is sometimes advantageous, especially when adhesive is used to secure the uppers in lasted relation to insoles, to apply pressure and heat to the margin of the upper overlying the insole after the lasting operation. In this manner the margin of the upper is pressed more firmly into adhering relation to the insole and the drying or setting of the adhesive is accelerated. Such application of pressure and heat, moreover, serves to eliminate any wrinkles that there may be in the margin of the upper and to provide an even surface for the reception of the outsole. Various features of the present invention are to be recognized in a novel organization of lasting means and pressing or ironing means whereby the lasting operation may be performed and immediately thereafter the margin of the upper may be conveniently subjected to such pressure and heat. For the purposes in view, the machine herein shown is provided with a shoe support whereby each shoe may be readily presented in proper relation to the means that operates thereon, means for lasting the forepart of the shoe at the rear of the toe portion, and a pressing or ironing device mounted for movement from an idle position to a definitely determined position opposite the bottom of the shoe prior to its operation on the shoe. More particularly, in the construction shown the arrangement is such that the shoe is positioned bottom upward with its toe end pointing toward

the rear of the machine, and the pressing device is mounted for forward swinging movement about a horizontal axis from an idle position nearer the rear of the machine than the shoe to a position over the bottom of the forepart of the shoe. Conveniently, and in order to insure against danger of applying excessive heat to the shoe, there is provided means for heating the pressing device only when it is in its idle position, the construction shown comprising a heater which is maintained yieldingly in contact with the device in that position and out of contact with which the device is carried in its movement into position over the shoe bottom. As above suggested, the pressing device of the illustrative machine is so constructed as to operate upon the margin of the upper throughout the length of the forepart, including the previously lasted toe portion, which is especially advantageous if the toe portion of the upper has been secured adhesively to the insole; although it is to be understood that the beneficial effect of the pressure and heat in pressing the margin of the upper smoothly upon the insole is not dependent upon the previous lasting of the upper with adhesive. For better insurance that the upper will be secured tightly about the edge of the insole and will be ironed smoothly upon the insole, the pressing device, as shown, operates with an inward wiping action on the margin of the upper at the opposite sides of the shoe bottom.

The invention further provides novel means whereby parts of the machine are operated by fluid pressure, the construction disclosed being such that fluid, preferably oil, maintained under predetermined pressure by a continuously operating pump, is utilized at the will of the operator to force the shoe against a holdown for controlling it in the lasting operation, to effect in part the operation of the lasting means, and thereafter to force the shoe against the pressing or ironing means. As further illustrated, mechanism is provided whereby the operator forces the shoe into contact with the holdown, and later into contact with the pressing means, prior to the action of the fluid pressure means to force the shoe more firmly against these parts.

Various features of the invention are further to be recognized in novel means for lasting the shoe. In the construction shown the upper is conformed to the contour of the forepart of the last by a flexible elastic apron which is stretched heightwise of the last by the above-mentioned fluid pressure means, and the margin of the upper is laid inwardly over an insole on the last by

means which acts through the apron and is conformable to the contour of the shoe bottom, this means, as illustrated, comprising at each side of the shoe a flexible cable arranged to extend lengthwise along the edge of the shoe bottom. As herein shown, each cable is operated by a treadle through movement of which also the fluid pressure means is rendered operative to stretch the apron. To facilitate the laying of the upper over the insole and to prevent wear of the apron by friction of the cables thereon, each cable is surrounded by a coil spring which may be turned relatively to it by contact of the apron therewith and relatively to which the cable is movable lengthwise. As further illustrated, the apron is forced or wedged by the cable into a space provided between the shoe bottom and a member which is located opposite the shoe bottom and acts as a deflector to increase the pressure of the cable and apron on the margin of the upper. In order further to prevent undue wear on the apron, and also to facilitate forcing the apron inwardly over the shoe bottom, mechanism is provided for causing the fluid pressure means to relieve the pull on the apron, this mechanism, as illustrated, being operated in response to force applied to the treadle after the apron has been forced far enough inwardly to insure against loss of control of the upper. The cable which operates at each side of the shoe bottom is maintained initially in an out of the way position and is carried inwardly to position it partially around the apron before the cable is operated as above described; and to avoid interference between the parts which operate at the opposite sides of the shoe bottom the construction disclosed is further such that the overlaying operation is performed on the margin of the upper first at one side of the shoe bottom and thereafter at the other side of the shoe bottom.

Still other features of the invention are to be recognized in novel shoe-pressing means. In accordance with one feature, the invention provides novel pressing or ironing means movable inwardly over the shoe bottom in wiping contact therewith and conformable to the contour of the shoe in response to pressure of the shoe thereon. In the construction shown such means comprises shoe-engaging plates which are flexibly conformable to the contour of the shoe, the plates being movable inwardly toward each other at the opposite sides of the shoe bottom in response to pressure of the shoe upon them. As further illustrated, two pairs of plates are thus provided, the two plates of each pair being arranged in superposed relation and having slits therein to increase their flexibility. In accordance with a further feature, shoe-pressing means which is conformable to the contour of the shoe is yet so controlled as to apply firm pressure to the shoe after its conformity to the shoe contour. For this purpose, in the construction herein shown, the flexible plates that operate at each side of the shoe bottom are backed up by a group of loose metal balls which adjust themselves to the contour of the shoe with the plates and thereafter become substantially fixed relatively to means which controls them so that they render the plates effective to apply firm pressure to the shoe. For confining each group of balls laterally the construction shown further comprises a row of pins which act as a fence around the balls and are yieldable in response to pressure of the plates thereon. It will be recognized that means other than metal balls may be utilized, if desired, for

the purpose in view. While the above-mentioned plates are heated by the means hereinbefore referred to, it is to be understood that in its provision of shoe-pressing means the invention is not limited to a construction for applying heat as well as pressure, since under some conditions there may be desirable advantages in the use of pressure alone, and further that the invention is not limited to means for applying pressure on the particular portion or surface of the shoe illustrated.

The above and other features of the invention, including various novel details of construction and combinations of parts, will now be more particularly described by reference to the accompanying drawings and pointed out in the claims.

In the drawings,

Fig. 20 is a perspective view of a shoe as it appears after having been operated upon by the machine.

The machine herein shown is a twin machine having two sets of operating instrumentalities arranged side by side for operating respectively on shoes in different locations in the machine. The two sets of instrumentalities may thus be conveniently used to operate respectively on right and left shoes, and conveniently also the lasting operation may be performed on a shoe by one set of instrumentalities while a previously lasted shoe is maintained under pressure of the ironing means by the other set of instrumentalities. Since the two sets are constructed substantially alike except for such differences as are required by their different locations, and since they are operated and controlled independently of each other,

other, the present description will be confined for the most part to that set which is at the right-hand side of the machine.

The last and shoe are supported in position for the operations of the machine by a work support shown in Fig. 6, comprising a last pin 10 which engages the heel end of the last in its spindle hole and a shoe rest 12, conveniently referred to hereinafter as a toe rest, which underlies the forepart of the shoe. The toe rest is hollowed out laterally to receive the shoe, as illustrated in Figs. 13 and 14, and comprises a rubber pad 14 mounted on a block 16 fast on the head 18 of a stud 20 (Fig. 9) which extends downwardly into an opening in a holder 22. The stud is not fast in the opening, so that the toe rest may turn and adjust itself to the shoe. The holder 22 is mounted to swing in directions lengthwise of the shoe on a rod 24 which is mounted in a plate 26 secured by a screw 28 (Fig. 6) to a bar 30 extending lengthwise of the shoe. As shown in Fig. 9, the left-hand portion of the rod 24 is of greater diameter than the portion which extends through the plate 26 and this enlarged portion abuts against one side of the plate. Rotatably mounted on the rod at the other side of the plate 26 is a sleeve 32 abutting at one end against the plate and threaded exteriorly to engage corresponding threads formed in a downturned portion of the holder 22, this sleeve having a knurled head 34 thereon for turning it. A washer 36 and a nut 38 mounted on a still further reduced portion of the rod 24 serve to confine the sleeve 32 on the rod and to hold the rod in place in the plate 26. It will be understood that by turning the sleeve 32 the holder 22 and the toe rest 12 thereon may be adjusted in directions widthwise of the shoe. A spring-pressed plunger 40 (Fig. 6) mounted in a socket in the holder 22 and engaging the top face of the plate 26 tends to swing the toe rest in a direction toward the heel end of the shoe, and cooperating with the spring to determine adjustably the position of the toe rest lengthwise of the shoe is a screw 42 threaded in a lug on the holder 22 and engaging the top of the plate 26. It will thus be seen that the toe rest may readily be adjusted in directions both lengthwise and laterally of the shoe as required by shoes of different sizes or styles.

The heel pin 10 is secured to a slide 44 (Figs. 6, 10 and 11) adjustably movable in directions widthwise of the shoe along guideways formed in a holder 46. Formed on one side of the slide 44 are teeth 48 arranged to be engaged by similar teeth formed on a detent member 50 which extends through an opening in the holder 46. The member 50 is pivotally mounted on a screw 52 threaded in the holder 46 and is provided with a handle 54 by which it may be swung against the resistance of a torsion spring 56 to release the slide 44 and permit the adjustment of the slide. As illustrated, the slide 44 is in a position in which the last pin 10 is laterally offset to the right of a vertical plane extending from front to rear centrally through the toe rest 12 so as to position a right shoe with the longitudinal median line of the forepart of the shoe bottom lying substantially in that plane. It will be understood that for positioning a left shoe for the operation of the left-hand set of instrumentalities the last pin will be laterally offset in the opposite direction, as illustrated at the left-hand side of Fig. 1. The holder 46 is mounted for swinging movements in directions lengthwise of the shoe on

a pin 58 supported in a lug 60 formed on a slide 62 (Fig. 10) adjustably movable along the bar 30, this slide being held on the bar by a plate 64 which is fast on one side of the slide. A spring 66 mounted in a socket in the holder 46 and engaging the slide 62 tends to tip the last pin in a direction away from the toe rest, and cooperating with the spring to determine adjustably the position of the pin is a screw 68 threaded in the holder 46 and engaging at its lower end the slide 62.

The bar 30 is fastened on the top of a holder 70 which has a lower segmental portion curved lengthwise of the shoe about an axis located approximately at the bottom face of the ball portion of the shoe. This segmental portion of the holder 70 is mounted on a correspondingly curved support 72 (Figs. 10 and 12) and is confined thereon by a plate 74 fast on the support. The support 72 has a depending sleeve 76 which is fast on the upper end of a rod 78 mounted for vertical movements in upper and lower bearings in the frame of the machine, the sleeve 76 resting initially on an arm 80 of the frame, as shown in Fig. 6, with the work support in a lowered position. The holder 70 and the parts supported thereon are adjustable along the curved guideway on the support 72 about the previously mentioned axis to position the bottom of the forepart of the shoe in the proper plane parallel to the lower face of a holdown plate 82 which is supported as hereinafter described. To facilitate such adjustment of the holder 70 there is fast on the front end of the bar 30 a handle 84. The holder is maintained in adjusted position by a spring-pressed pin 86 (Fig. 12) slidably mounted in a thimble 88 in the support 72 and arranged to enter any one of a number of holes 90 provided in one side of the segmental portion of the holder 70. The inner end of the thimble 88 lies in a curved slot 92 (Figs. 6 and 10) formed in the side of the holder 70 to assist in confining the holder on its guideway on the support 72. When it is desired to adjust the holder the operator pulls the pin 86 outwardly by engaging a head 94 (Fig. 12) on the pin.

As above suggested, the slide 62 which carries the last pin 10 is movable along the bar 30 to position the last pin in proper relation to the toe rest for shoes of different lengths. To hold the slide in the position to which it is thus moved there are formed on the lower edge of the plate 64 which is fast on the slide a series of teeth 96 (Fig. 6) engaged by similar teeth on the upper end of a detent 98 which is slidably movable upwardly and downwardly in a guideway in the holder 70 and is confined by a plate 100 fast on the holder. A pin 101 projecting from the detent into an enlarged opening in the plate 100 limits downward movement of the detent. At its lower end the detent 98 has an extension 102 provided with a lower face curved about the same axis as the segmental portion of the holder 70 and engaging a similarly curved upper face of a segment 104 provided with a depending portion 106 which is vertically movable in a guideway formed in an offset portion of the plate 74. A light spring 108 mounted in a socket in the holder 70 and engaging the extension 102 of the detent 98 tends to force the detent downwardly and maintains its extension 102 in engagement with the segment 104. Another light spring 110 mounted in the plate 74 and engaging a pin 112 which projects laterally from the depending portion 106

of the segment 104 tends to force this segment downwardly. It will thus be seen that when permitted the springs 108 and 110 will cause the detent 98 to release the slide 62 and thus permit the operator to move the slide along the bar 30. To maintain the detent in position to hold the slide 62 against movement along the bar 30 the pin 112 is upraised by a bell-crank lever 114 one arm of which underlies the pin and is controlled by a spring 116 of sufficient strength to overcome the two light springs 108 and 110. The bell-crank lever 114 is pivoted at 118 on a short arm 120 of a lever 122 which is pivoted at 124 on the depending sleeve portion 16 of the support 72 and is utilized for a purpose hereinafter described, the spring 116 being mounted in a socket in the arm 120. The bell-crank lever 114 is connected by a link 126 (Fig. 2) to a handle 128 pivoted at 130 on a depending lug on the lever 122. It will thus be seen that when the operator raises the handle 128 the latter acts through the link 126 to swing the bell-crank lever 114 against the resistance of the spring 116 and thus to permit the pin 112 to move downwardly so that the spring 108 forces the detent 98 away from the teeth on the plate 64. After the operator has moved the slide 62 to the desired position he releases the handle 128, whereupon the spring 116 forces the detent again into locking relation to the slide. It will be evident that the segment 104 maintains its controlling relation to the detent 98 in all positions of adjustment of the holder 70 along its curved guideway in the support 72.

35 Since the locations of the spindle holes in the heel ends of lasts frequently vary even in lasts of the same style and size, and in order also to facilitate presentation of the work, it is contemplated that the slide 62 will preferably occupy a position substantially at the forward end of the bar 30 to receive each last and shoe. The operator will then move the slide with the shoe toward the toe rest to present the shoe in proper position, holding the handle 128 upraised so that 40 the slide is unlocked to permit this to be done. To assist the operator in determining when the shoe is in the proper lengthwise position there is provided a gage 132 (Figs. 6 and 8) the forward end of which is arranged to indicate the proper 45 lengthwise position of the shoe by reference to the ball line of the shoe. The gage 132 is located somewhat above the shoe bottom at the time of presentation of the work, as indicated in Fig. 6, but is so arranged in relation to the operator's 50 line of vision as he stands in front of the machine that it enables him to determine by sight with sufficient accuracy when the shoe is properly positioned. As will be evident hereinafter, the character of the means provided for operating on the 55 shoe is such as not to require that the shoe be positioned either lengthwise or laterally with a very high degree of accuracy. The gage 132 is supported by a plate 134 which is spaced a substantial distance above the previously mentioned 60 holdown plate 82 for a purpose hereinafter described. Both plates 82 and 134 are supported on the forward end of an arm 136 mounted as also hereinafter described, and the plate 134 is confined between a shoulder on the arm and a 65 shoulder on a member 138 on the lower end of which the plate 82 is secured (Fig. 13). The member 138 has an upwardly extending hollow stem 140 mounted in an opening in the arm 136 and fastened to the arm by a nut 142, the member 138 70 being held from turning by a pin 144 (Fig. 6)

which projects from the arm 136 into a slot 146 in the stem 140. Within this hollow stem is a rod 148 on the upper end of which is mounted a handle 150 for use in controlling the arm 136 in a manner hereinafter explained. The gage 132 is supported on the plate 134 by means of another plate 152 which rests on the plate 134 and is pivoted for swinging movements laterally of the shoe on a screw 154. Fast on the forward end of the plate 152 is a pin 156 on the lower end of which the gage 132 is secured, this pin extending through a slot 158 in the plate 134. This slot is wide enough to permit some swinging movement laterally of the shoe of the plate 152 and the gage 132 to afford sufficient room for the laying of the margin of the upper inwardly over the shoe bottom, first at one side and then at the other side of the shoe bottom, as hereinafter described.

After the operator has presented the work in the manner above explained he raises the work support to carry the forepart of the shoe bottom into engagement with the holdown plate 82. For this purpose a downwardly extending arm 160 (Figs. 1 and 2) of the hand lever 122 is forked at its lower end and connected to a wedge member 162 by means of pins 164 which project from the forked arm into vertical slots 166 in the opposite sides of the wedge member. The wedge member 162 is slideable along guideways provided in a block 168 mounted as hereinafter described and in which the work support rod 78 is slidably movable, and in engagement with the upper face of the wedge member is a collar 170 fast on the rod 78. It will thus be seen that by depression of the hand lever 122 the wedge member 162 is forced 35 inwardly between the block 168 and the collar 170 and thereby serves to force the work support upwardly to bring the bottom of the shoe into engagement with the holdown plate 82. Since the hand lever 122 is pivotally mounted, as hereinbefore described, on a part of the vertically 40 movable work support, the guideways on the block 168 are upwardly inclined so that the wedge member 162 receives some upward movement as it is operated to raise the work support. After the 45 operator has raised the work support by depression of the hand lever 122, the friction between the wedge member 162 and the parts which it engages is sufficient to maintain the support in its elevated position relatively to the block 168. 50 To prevent turning of the work support about the axis of the rod 78 the member 72 on which the segmental part of the member 70 is supported has thereon a lug 172 (Fig. 6) extending rearwardly therefrom between opposite guiding faces, 55 one of which is shown at 174, on a bracket 175 on the frame of the machine.

As hereinbefore suggested, the machine herein shown is designed to operate upon a shoe which 60 has already been lasted at the toe-end portion and at the waist or shank portion, and is provided with means for lasting the forepart of the shoe between these previously lasted portions. This means comprises a flexible lasting apron 176 arranged to extend across the top of the forepart of the shoe between the shoe and the toe rest 12 and also to extend upwardly at both sides of the forepart, the apron preferably consisting of a sheet of rubber molded to provide a hollow 65 to receive the shoe. As shown in Fig. 6, the apron has a stem 177 thereon which extends into a hole in the toe rest pad 14 to fix its position relatively to the toe rest. The apron may, as shown, 70 extend about the toe portion of the shoe as well as about the forepart at the rear of the toe, and 75

it preferably is of sufficient length to overlap more or less previously lasted portions of the upper at the waist of the shoe. The apron 176 overlies the toe rest 12 at all times and is therefore engaged by the shoe when the operator presents the work to the machine. Through this apron, moreover, pressure is applied to the top of the forepart of the shoe by the toe rest when the shoe is clamped against the holdown plate 82, the toe rest extending far enough toward the heel end of the shoe to conform the top of the forepart of the upper at the rear of the toe to the contour of the top face of the last which is more or less concave lengthwise of the last in that location. The opposite side edges of the apron 176 are clamped between plates 178 (Figs. 13 and 14), and in these plates are openings 180 whereby the plates and the apron are suspended on hooks 182. By reference to Fig. 4 it will be seen that in each pair of plates there are three holes 189 which may be utilized selectively to receive the corresponding hook 182 under different conditions. The hooks 182 are carried by arms 184 (Figs. 1, 4 and 6) which are mounted 25 to turn freely on reduced upper end portions of rods 186 mounted for upward and downward movements in bearings formed in lugs 188 and 190 on the bracket 175. These bearings, it will be seen, are so arranged that the rods 186 are inclined upwardly and forwardly toward the front of the machine. To conform the forepart of the upper tightly to the last at the rear of the toe portion the apron 176 is stretched by upward movement of the rods 186 in such forwardly inclined directions, in the course of which upward movements the arms 184 are permitted to turn about the upper ends of the rods so that they assume positions determined by the action of the rubber apron thereon. When the apron is thus stretched the portion thereof at each side of the shoe is inclined somewhat outwardly from the side of the shoe as indicated at the left-hand side of Fig. 13.

The upward movements of the rods 186 to stretch the apron 176 as above described are effected by power through the action of fluid pressure means. For this purpose each rod 186 has fast thereon a collar 192 (Figs. 1 and 6) to which there is pivotally connected an operating link 194. The right-hand link 194 is connected to an arm 196 (Fig. 2) which is fast on a rock shaft 198 mounted in bearings in the frame, and the left-hand link (Fig. 1) is connected to an arm 200 also fast on this rock shaft. The arm 200 has integral therewith a downwardly curved arm 202 which is pivotally connected to the upper closed end of a cylinder 204. This cylinder is slideable upwardly and downwardly on a piston 206 (Fig. 3) which has therein a central bore 208 communicating at its lower end with a transverse passage 210. At its lower end the piston 206 has a curved face 212 resting on a correspondingly curved seat formed at the bottom of a tank or reservoir 214 which is partially filled with liquid, preferably oil, as illustrated in Fig. 2. It will thus be seen that the piston 206 may swing laterally in the upward and downward movements of the cylinder 204 as required by the connection of the cylinder with the lever arm 202. A stop screw 216 engages one side of the lower end portion of the piston 206 to hold it against lateral displacement, and extending into the passage 210 at the opposite side of the piston is a pipe 218 about which the piston swings. Communicating 70 with the pipe 218 is a telescopic pipe 220 which

leads upwardly to a short horizontal pipe 222 (Fig. 4) leading into an opening 224 (Fig. 5) in a valve unit 226 by which the flow of oil to the piston 206 is controlled. Oil is supplied under pressure by a gear pump 228 (Fig. 4) driven continuously through a belt 229 by an electric motor 230, the oil being drawn from the tank 214 through a pipe 232 leading to the pump and being discharged from the pump through a pipe 234. The pipe 234 discharges the oil into a passage 236 communicating with another passage 238 which leads into the valve unit 226. The oil takes a course indicated by the arrows on Fig. 5 toward the upper face of an inlet valve 240 arranged to cooperate with a valve seat 242, this valve having a depending stem 244 slidably mounted in a bore formed in an upwardly extending hollow stem 246 of another valve 248 arranged to cooperate with a valve seat 250 around an outlet at the lower end of the unit 20 236. A light spring 252 in the hollow stem 246 tends to force the valve 240 upwardly and the valve 248 downwardly. The valve 240 is opened by pressure of the oil against it when permitted by valve-controlling means hereinafter described, 25 at which time the valve 248 is closed so that the oil under pressure passes through the opening 224 and into the hollow piston 206. The oil therefore acts to raise the cylinder 204 and thereby to operate the lasting apron 176 in the manner 30 hereinbefore described. In order to limit the stretching of the apron, there is a pressure control valve 254 (Fig. 4) cooperating with a valve seat 256 in a valve casing 258 to control a by-pass 259 leading from the pipe 234 back to the tank 35 214. The valve 254 has a stem 260 slidably mounted in a member 262 which is threaded in the valve casing 258, and between this member and the valve 254 is a spring 264 which tends to close the valve. It will be understood that the 40 valve will open when the pressure of the oil thereon is sufficient to overcome the resistance of the spring 264, which resistance may be varied by turning the member 262. The apron 176 will accordingly be stretched until its resistance to 45 the movement of the cylinder 204 is greater than the resistance of the spring 264 to the opening of the valve 254, whereupon the valve will open and permit the oil to circulate. Thereafter the apron will be held stretched under the force thus pre- 50 determined until such time as the valve 240 is closed and the valve 248 is opened, whereupon the oil is permitted to escape from the cylinder 204 past the valve 248 and into the tank 214 and the parts which operate the apron 176 return to 55 their starting positions. It will be understood that the oil circulates through the by-pass 259 at all times when the valve 240 is closed.

The valves 240 and 248 are controlled by a lever 266 (Figs. 4, 5 and 7) pivotally mounted on 60 an arm 268 of the valve unit 226 and arranged to engage the lower end of a rod 270 extending downwardly from the valve 248. The lever 266 is connected by a link 272 to one arm of a bell-crank lever 274 pivoted on a rod 276 on the 65 frame of the machine, the other arm of this bell-crank lever being connected by a link 278 to a lever 280 pivotally mounted on a rod 282 on the frame. Connected to the lever 280 is a link 284 provided with a slot 286 into which projects a pin 70 288 carried by a treadle 290 mounted to swing about a rock shaft 292 at the base of the machine, the treadle being held in its normally uprighted position by a spring 294. When the treadle is in this position the pin 288 acts on the link 284 and 75

the parts connected therewith to hold in depressed condition that arm of the lever 266 to which the link 272 is connected and thereby to maintain the valve 248 in open position and the valve 240 is closed position as illustrated in Fig. 5, the upper end of the valve stem 246 engaging the valve 240 to hold it closed. When the operator depresses the treadle 290 the pin 288 is carried downwardly, thus permitting the valve 248 to be closed by the combined action of the spring 252, of gravity and of the pressure of the oil and permitting the valve 240 to be opened by such pressure. Such movements of the valves occur at the beginning of the downward movement of the treadle and result in the stretching of the lasting apron 176 in the manner hereinbefore described, after which the treadle is further depressed for another purpose as will be explained. It will be understood that when the treadle is released by the operator it acts in its return to starting position to close the valve 240 and open the valve 248 and thus to permit the apron and the parts which control it to return to their starting positions.

It is desirable that during the lasting operation the shoe be pressed against the holdown plate 82 more firmly than the operator can conveniently press it by means of the hand lever 122, and accordingly fluid pressure means also controlled by the depression of the treadle 290 is provided for forcing the work support in an upward direction. For this purpose there are pivotally mounted on a rod 296 (Figs. 1 and 2) at the front of the frame of the machine two levers 298 and 300 which are connected to opposite sides of the block 168 in such manner as to raise this block when the levers are swung upwardly. It will be understood that when the block 168 is thus raised it acts through the wedge member 162 to raise the shoe support rod 78 and the parts thereon. At their rear ends the levers 298 and 300 are pivotally connected to a cylinder 302 within which is a hollow piston 304 mounted at its lower end to rock in a bearing in the tank 214 in the same manner as the previously described piston 206 (Fig. 3). The cylinder 302 and the piston 304 and the parts associated therewith are, in fact, constructed for the most part substantially like the parts shown in Fig. 3 for operating the lasting apron, and accordingly the construction is not illustrated in detail. The oil is conducted to the lower end of the piston 304 through a pipe 306 (Figs. 2 and 4) leading from a valve unit 308 of substantially the same construction as the valve unit 226 previously described and shown in Fig. 5. The valve unit 308 communicates through a passage 309 (Fig. 4) with the passage 236 leading from the pump. It will be understood that in this valve unit there is an inlet valve similar to the valve 240 shown in Fig. 5, and an outlet valve, similar to the valve 248, controlling a passage leading from the valve unit back to the tank 214. These valves are controlled by a lever 310 (Figs. 2, 4 and 7) which is connected by a link 312 to one arm of a bell-crank lever 314 pivoted on a rod 315 on the frame. A spring 316 connected to this bell-crank lever tends to depress the link 312 and thereby maintains the lower outlet valve in the valve unit 308 in open position and the upper inlet valve in closed position. Swiveled on one arm of the bell-crank lever 314 is a block 318 in which there is slidably mounted a rod 320 connected at its lower end to one arm of a bell-crank lever 322 pivotally mounted on the previously mentioned rod 276.

Mounted on the rod 320 is a sleeve 324 the upper end of which is arranged to engage the block 318 and the lower end of which is supported on a nut 326 (Fig. 2) on the rod. It will thus be seen that when the rod 320 is raised by the bell-crank lever 322 it acts through the sleeve 324 to operate the bell-crank lever 314 and thereby to raise the link 312 to cause the valve at the lower end of the valve unit 308 to close and the upper valve to open, whereupon the cylinder 302 is operated to raise the shoe support in a manner which will be readily understood from the previous description of the means for operating the lasting apron, the amount of force applied to the shoe support being determined by the pressure control valve 254 (Fig. 4).

For operating the bell-crank lever 322 there is connected to one arm of the lever a link 328 (Fig. 7) which is also connected to an arm 330 pivoted on the rod 282, and pivoted to this arm 20 is a link 332 provided with a slot 334 into which extends the previously mentioned pin 288 carried by the treadle 290. The spring 316 acts through the link 312 and the lever 310 to hold the valve at the lower end of the valve unit 308 normally 25 open and the upper valve closed, as previously explained, the connections between the bell-crank lever 314 and the treadle 290 being such that the valves are not held in these positions by the treadle when the latter is in its initial position because of the sliding connection between the swivel block 318 and the rod 320. To cause the lower valve to close and the upper valve to open, therefore, when the treadle is depressed, it is necessary to operate the bell-crank lever 314 against the 30 resistance of the spring 316, and for this purpose there is connected to the link 332 a comparatively strong spring 336 which is also connected to the treadle and acts upon depression of the treadle to pull the link downwardly and thus to elevate 40 the rearwardly extending arm of the bell-crank lever 314 through the action of the sleeve 324 on the block 318. It will be evident that the fluid pressure means for forcing the shoe support upwardly is thus rendered effective early in 45 the depression of the treadle 290 at substantially the same time when the fluid pressure means previously described for operating the lasting apron is rendered effective on the apron.

After the shoe support has been forced upwardly and the lasting apron has been stretched as above described to conform the unlasted portion of the forepart of the upper to the contour of the last, it is necessary to lay the margin of this portion of the upper inwardly over the insole 55 into position to be secured to the insole by cement previously applied to the margin of the upper materials or to the insole. For this purpose there are provided two flexible cables 338 (Figs. 4 and 6) which extend lengthwise along 60 the edge of the shoe bottom and act through the apron 176 at the opposite sides of the shoe respectively to lay the margin of the upper over the insole and press it upon the insole, as illustrated with reference to one side of the shoe 65 in Figs. 13 and 14. These cables may be made, for example, of twisted strands of flexible metal, and as illustrated the portion of each cable which acts on the lasting apron extends through a coil spring 340 which loosely surrounds it and engages the apron. The spring may turn more or less on the cable in response to the frictional action of the apron thereon in laying the upper over the insole, and as the cable is pulled as hereinafter described it slides lengthwise relatively 70 75

to parts of the spring which are in contact with the apron. The spring thus facilitates movement of the apron by the cable and lessens the wear on the apron. Each cable 338 at its forward end is connected to a block 341 (Fig. 6) swiveled on an arm 342 fast on a stud 344 (Fig. 2) which is mounted to turn in a hand lever 346, and connected to the lower end of this stud is a torsion spring 348 which tends to hold the arm 342 outward against a pin 350 (Fig. 4) on the lever 346. Each lever 346 is mounted for swinging movements laterally of the shoe on an arm of the previously mentioned bracket 175 and also for limited lengthwise movement relatively to a bolt 352 which extends through a slot 354 (Fig. 4) in the lever and has a head 356 with straight sides extending lengthwise of the lever in a guideway in the lever. The bolt 352 is mounted to turn in the arm of the bracket 175 as the lever 346 is swung inwardly to carry the cable 338 toward the lasting apron 176, and when the lever has been swung inwardly far enough to carry its rear end outwardly beyond a lug 358 (Fig. 4) on the bracket 175 the operator 20 pushes the lever lengthwise toward the rear of the machine as far as permitted by the bolt 352 and the slot 354 to engage an inner face 360 on the rear end of the lever with the outer face of the lug 358, so that the arm of the lever 25 which carries the cable is locked against reverse outward swinging movement. When the lever 346 is in this position the cable 338 connected to it, which is further controlled as hereinafter described, is held inwardly against the lasting apron 176, the arm 342 extending inwardly over the shoe bottom and holding the cable wrapped 30 in a curve about that portion of the apron which is located at the beginning of the waist portion of the shoe. Only one of the levers 346 at a 35 time is maintained in this position, in order to avoid interference of the arms 342 with each other.

As shown in Fig. 4, the two cables 338 are arranged to extend both lengthwise and laterally of the shoe and are crossed in a location beyond the toe end of the shoe. Each cable further extends over a grooved pulley 362 supported by a bracket 364 (Fig. 6) which rests on the bracket 175 and has a depending stem 366 swiveled in an opening in this bracket so that the pulley with its supporting bracket 364 may turn about a vertical axis to adapt its position to the position of the cable. The cable extends downwardly through an opening in the stem 366 and is connected at its lower end to one arm of a bell-crank lever 368 (Fig. 2) pivotally mounted on a rod 370 on the frame. It will be understood that each cable is thus connected to a separate bell-crank lever 368, as shown in Fig. 1. The operation of each cable to lay the margin of the upper inwardly over the insole is effected by swinging the bell-crank lever 368 connected thereto in the direction to pull downwardly on the lower end of the cable, and this is accomplished by further depression of the treadle 293 after its initial depression to cause the shoe to be clamped firmly against the holdown plate and the lasting apron to be stretched by the fluid-pressure means as hereinbefore described. For this purpose there is pivotally connected at 372 to a depending arm of each lever 368 a link 374 which at its lower end is pivotally connected by a stud 376 to one arm of a bracket 378 (Fig. 7) pivoted by means of a rod 380 upon the rear end 75 of the treadle 290. When the treadle is de-

pressed, therefore, both bell-crank levers 368 are swung thereby to pull downwardly on the lower ends of the cables 338 and thus to draw or pull the portions of the cables which are opposite the lasting apron 176 lengthwise and laterally of the shoe, the arms 342 which support the forward ends of the cables swinging toward each other about their connections with the levers 346 against the resistance of the springs 348 in response to the pull of the cables thereon. Since only one of the cables, however, has been carried inward against the apron by movement of its lever 346, as above explained, the other cable when operated by the treadle is ineffective upon the apron to lay the margin of the upper over the insole at that side of the shoe bottom. It will be understood that the pull applied to the cable which is effective on the apron tends to straighten the portion of the cable previously referred to as wrapped in a curve about that portion of the apron which is located at the beginning of the waist portion of the shoe, while at the same time the arm 342 connected to that portion of the cable is swung by the pull of the cable thereon in a direction to carry the cable still farther inwardly over the shoe bottom. The apron is thus rendered effective to lay tightly inward over the insole that portion of the margin of the upper where the side of the last curves inwardly toward its waist portion, as well as the portions of the margin of the upper extending forwardly to the toe-end portion of the shoe. As illustrated in Figs. 13 and 14, the cable when thus operated acts to force or wedge the rubber apron inwardly between the shoe bottom and the previously mentioned plate 134, the plate having a beveled lower face and acting as an abutment or deflector to force the cable downwardly and thus to increase the pressure of the apron on the upper so as to render the apron more effective to draw the upper tightly inward over the edge of the insole and to press it firmly down upon the insole.

In order to facilitate the laying of the margin of the upper inwardly over the insole by each cable 338 through the operation of the treadle, and to avoid undue stretching of the rubber apron 176 and also excessive inward strain of the apron on the margin of the upper such as might tend to displace the margin of the insole, there is further provided means for relieving the upward pull of the arms 184 on the apron by closing the valve 240 and opening the valve 248 of the valve unit 226 (Fig. 5) associated with the cylinder 204 (Fig. 3) which operates the apron. For this purpose there is connected to a depending arm of the lever 280 (Fig. 7) a link 382 provided with a slot 384 through which extends a pin 386 projecting from one of the studs 376. It will be understood that when the link 284 connected to the lever 280 is released by the pin 288 in the initial depression of the treadle 290 as hereinbefore described, the link 382 is moved far enough by the lever 280 to cause the pin 386 to lie at the forward or left-hand end of the slot 384 (Fig. 7). The valve 240 accordingly may thereafter be closed and the valve 248 opened by forward movement of the link 382 derived from movement of the pin 386. Such movement of the pin is effected by swinging the bracket 378 on the treadle about the axis of the rod 380, the swinging of the bracket resulting from the force applied thereto by the treadle because of the fact that the pivotal connections 376 between the bracket and the lower ends of the links 374 75

are offset forwardly from straight lines extending from the rod 380 to the pivotal connections 372 (Fig. 2) between the upper ends of the links 374 and the bell-crank levers 368. The tendency 5 of the force applied by the treadle accordingly is to swing forwardly the upwardly extending arms of the bracket 378, on one of which the pin 386 is mounted, and also the lower ends of the links 374. Such swinging movement of the bracket is 10 limited by studs 388 carried by the links 374 and extending through slots 390 in the arms of the bracket, and is against the resistance of springs 392 which are adjustably connected to the links and to the arms of the bracket and hold the parts 15 initially in the positions indicated in Fig. 7 with the studs 388 at the left-hand ends of the slots 390. These springs do not yield until after the apron 176 has been forced far enough inwardly to be gripped between the shoe bottom and the 20 plate 134, as illustrated in Fig. 13, so as to insure against loss of control of the upper when the pull on the apron is relieved. When the springs yield the valves are operated as described and the arms 184 which act on the apron are moved downwardly 25 and lower the side portions of the apron, as shown in Fig. 14. It will be understood that both the opposite side portions of the apron are thus lowered, although a cable is acting only at one side thereof. As the treadle is further depressed, the apron is forced farther inwardly 30 over the shoe bottom by the cable, as illustrated in Fig. 14. When, thereafter, the operator releases the treadle enough to relieve the pull on the cable 338, the bracket 378 is swung back to 35 its normal position by the springs 392, so that the valve 240 is opened again by the pressure of the oil thereon and the valve 248 is closed to cause the apron again to be stretched upward by the arms 184, the operator maintaining the 40 treadle far enough depressed to permit this action of the valves. This stretching of the apron assists in withdrawing the cable 338 from between the shoe bottom and the plate 134. Thereafter the lever 346 at the other side of the shoe 45 is swung inwardly and locked and the treadle is again fully depressed to effect the overlaying of the margin of the upper in the same manner at that side of the shoe. The operator then fully releases the treadle, and in response to its return 50 upward movement the valves controlling the fluid-pressure means which operate the lasting apron and the shoe support are returned to their starting position so that the sides of the lasting apron are dropped and the upward pressure 55 of the shoe on the holdown plate 82 is relaxed. Thereafter the operator lifts the hand lever 122 to withdraw the wedge 162 and thereby permit the shoe to be lowered out of contact with the holdown plate preparatory to the ironing 60 operation on the forepart of the shoe bottom.

By reference to Figs. 4 and 6 it will be seen that the two cables 338 extend through a slot formed in a guide 394 having rearwardly extending arms which are pivoted on a rod 396 mounted on a holder 398 fast on the bracket 175. A light torsion spring 400 tends to swing the guide 394 downwardly so that it is supported at its forward end on the cables 338 when 65 the parts are in their normal positions. Connected to an arm 402 which extends downwardly from the guide 394 and also to the hub of one of the arms 184 which carry the lasting apron 176 is a spring 404 which is tensioned by the upward 70 movement of the arm 184 to stretch the apron. 75

Through this spring therefore the guide 394 is swung upwardly at that time against the resistance of the light spring 400 and serves to lift the cables 338 so as to insure that when each cable is operated to lay the margin of the upper 5 over the insole it will be located at the proper height to be pulled inwardly over the shoe bottom.

The means for pressing or ironing the bottom of the forepart of the shoe after the lasting 10 operation comprises a device supported on two bars 406 (Figs. 1 and 2) which are fastened at their lower ends to the previously mentioned rockshaft 292 on which the treadle 290 is loosely mounted, so that the device may be swung forwardly from an idle position to a position over 15 the shoe bottom. By means of trunnions 408 (Fig. 16) the bars 406 support at their upper ends a casting 410 which is fast on the trunnions and by which two ironing units are supported as 20 hereinafter described. In the ironing operation the casting 410 and the ironing units thereon may swing about the axis of the trunnions 408, i. e., an axis extending laterally of the shoe, for 25 better conformity of the ironing units to the lengthwise contour of the shoe bottom. The casting 410, however, is held normally in a pre-determined position with respect to movement about this axis by springs 412 which are mounted in sockets in enlarged upper end portions of the 30 bars 406 and press upwardly against lugs 414 on the casting, as shown in Figs. 2 and 15. On the front of the casting 410 is secured the arm 136 which supports the holdown plate 82 as hereinbefore described. On the rear of the casting is 35 secured an arm 416 in the rear end of which is threaded for upward or downward adjustment a stud 418 the lower end of which is in position to engage a plate 420 fast on the frame of the machine when the bars 406 are at the limit of their 40 rearward movement determined by engagement of the bars with studs 422 on the frame, one of these studs being shown in Fig. 2. By its engagement with the plate 420 the stud 418 serves to prevent any substantial tipping movement of 45 the casting 410 about the axis of the trunnions 408 when the shoe is pressed up against the holdown plate 82, and acts positively to hold this plate against the upward pressure of the shoe thereon. The plate 420, however, opposes no substantial 50 resistance to the forward swinging movement of the casting 410 into position over the shoe bottom.

Within the casting 410 there is another casting 424 (Figs. 15 and 16) which is mounted on a 55 rod 426 for swinging or tipping movements about an axis extending lengthwise of the shoe, this rod being secured at its ends to the casting 410. The casting 424 is maintained normally in a pre-determined position with respect to such tipping 60 movement by springs 428 mounted in sockets in the castings 410 and 424. Supported on the casting 424 are the two ironing units arranged to act respectively at the opposite sides of the shoe bottom and each comprising a holder 430 65 on which are secured by screws 432 a pair of flexible resilient ironing plates 434 (Fig. 18), these plates being arranged in superposed contiguous relation. Extending inwardly from one edge of each of the plates 434 in directions parallel to 70 the direction of ironing movement of the plates are a plurality of slits 436 which divide the plate into a series of fingers 438, the slits in the different plates being staggered so that the fingers of the upper plate overlap the slits in the lower 75

plate. By reason of this construction the plates are rendered more flexible to permit them to conform readily to the contour of the shoe bottom. At their outer edges, i. e. the edges that 5 are farthest from the shoe, the two plates of each pair are embraced by a retainer 440 through which the screws 432 act to secure the plates to the holder 430. Near the inner edges of each pair of plates there are fastened to the 10 lower plate angular clips 442 (Fig. 18) the upper end of each of which is arranged to extend into a slot 444 in the holder 430 and over a ledge 446 on the holder to limit downward movement of the inner end portions of the plates. It will be 15 understood that when the shoe is pressed against the ironing means the slots 444 permit the plates to yield upwardly. The plates 434 are arranged to act not only on that portion of the margin of the upper which is laid inwardly over the insole 20 by the lasting means, but also on the margin of the previously lasted toe portion of the upper, and preferably extend somewhat forwardly and rearwardly of the forepart of the shoe.

Each holder 430 is suspended on the casting 25 424 by a pair of links 448 and 450 (Fig. 19) at the front of the casting and by another such pair of links (Fig. 15) at the rear of the casting. Each link 448 is pivotally mounted on a pin 452 on the casting 424 and is pivotally connected to 30 the holder 430 by a pin 454. Each link 450 is pivotally mounted on a pin 456 on the casting and is pivotally connected to the holder by a pin 458. The two links 448 and 450 of each pair constitute, in effect, parallel links, and it will be evident from Figs. 16 and 19 that the arrangement 35 of the links is such that in downward movements of the two holders 430 relatively to the casting 424 the holders swing outwardly away from each other and in upward movements relatively to the casting they swing inwardly toward each other. The two holders are forced downward and outward by spring-pressed plungers 460 and 462 mounted in the casting 424, the movements of the holders in these directions being limited by 40 pins 464 extending into slots 465 in the holders as illustrated in Fig. 16. It will be understood that when the shoe is forced upwardly against the ironing plates 434 the plungers 460 and 462 yield, thus permitting the plates at the opposite 45 sides of the shoe bottom to be forced inwardly toward each other with a wiping action on the overlasted margin of the upper in response to the pressure of the shoe on the plates. Such upward and inward movements of the holders 50 430 are positively limited by contact of the holders with the casting 424, as illustrated in Fig. 19.

It will be understood that when the shoe is pressed upwardly against the ironing plates 434 they are flexed by the pressure of the shoe thereon to conform to the contour of the shoe bottom, and that the castings 424 and 410 may tip more or less about their respective axes to facilitate conformity of the plates to the contour of the shoe. To provide for the application of more effective pressure by the plates to the shoe, there is further arranged above each pair of plates a group of metal balls 466 resting on the upper plate and partially filling a recess 468 in the holder 430. Arranged in a series entirely around the group of balls are parallel vertical pins 470 which are slidably movable in the holder 430 and rest at their lower ends on the upper plate 434, the pins being pressed downwardly by springs 472 which are mounted in sockets in the holder 430. It will be understood that the pins are near

enough together to prevent escape of the metal balls and serve as a fence around the group of balls. When the shoe is pressed against the ironing plates the latter yield upwardly and are flexed to conform to the contour of the shoe, 5 pressing the pins 470 upwardly until the balls 466, which adjust themselves in accordance with the contour of the shoe, completely fill the recesses 468 in the holders 430. The balls are then fixed relatively to the holders by the pressure 10 against them and serve as positive means to prevent any further upward yield of the plates relatively to the holders, thus rendering the plates effective to apply increased pressure to the margin of the upper.

When the ironing means is in its idle position, as shown in Fig. 2, the ironing plates 434 are over and in contact with a heater 474 whereby they are maintained in a heated condition. This heater is secured to a bar 476 (see also Fig. 4) 20 having forwardly extending arms 478 pivotally mounted on pins 480 supported by lugs 482 on the bracket 175. The heater is thus permitted to swing upwardly and downwardly. Light springs 484 mounted under the forward ends of the arms 478 and supported by the bracket 175 tend to swing the heater upwardly, and when the ironing means is swung rearwardly from its position over a shoe the ironing plates 434 engage the forward end portion of the heater and depress it somewhat against the resistance of these springs, after which the springs maintain the heater yieldingly in contact with the plates. Upward swinging movement of the heater is adjustably limited by a stop screw 485 carried by the 30 bar 476 and arranged to engage the bracket 175. Within the heater 474 is an electrical heating unit 486, and fast on the bar 476 at the rear of the heater is a box 488 into which extend electrical conductors connected with the heating 40 unit.

The operator swings the ironing device forwardly to its position over the shoe by the previously mentioned handle 150, its forward movement being limited by contact of a stop face 490 45 (Fig. 2) on one of the bars 406 with a block 492 mounted on a rod 494 on the frame. As shown in Fig. 6, the block 492 is a substantially square block which is eccentric to the rod 494 and is mounted to turn around the rod so that different sides of it may be in position to stop the forward movement of the ironing device and thus to vary the position of the device. A spring-pressed ball 496 carried by the block is arranged to enter any one of four depressions in the rod 494 to 50 maintain the block in adjusted position. Two bosses 498 (Figs. 1 and 2) on the frame are arranged to engage inner faces on the bars 406 to assist in preventing any swinging of the bars laterally of the machine in the ironing operation. 60 The ironing device is partially counterbalanced by torsion springs 500 which are coiled around the rock shaft 292 and tend to swing the bars 406 forwardly, thus rendering it easier for the operator to swing the device into operative position.

When the ironing device is in its position over the forepart of the shoe bottom the operator forces the shoe upwardly against it by depression of the previously mentioned hand lever 122, and there- 70 after the shoe is forced farther upward by the previously described fluid pressure means provided for raising the shoe support. In order to render this fluid pressure means operative to raise the shoe support at this time, there is provided a 75

bar 502 (Fig. 7) slidably movable in a bearing in the frame and having an upturned forward end for manipulating it, this bar being connected at its rear end by a pin 504 to the bell-crank lever 314 which controls the valves in the valve unit 308. By pulling the bar 502 forwardly the operator may elevate the link 312, thereby causing the upper valve of the valve unit to open and the lower valve to close as will be readily understood from the previous description of these parts.

10 The oil is thereupon forced into the cylinder 302 to raise the shoe support and cause the ironing means to act on the margin of the upper with an inward wiping and pressing action as hereinbefore described. It will be understood that the forward movement of the bar 502 does not affect the connections between the bell-crank lever 314 and the treadle, since the block 318 slides upwardly along the rod 320 without imparting any movement to this rod. The bar 502 is maintained in its forward position by a spring-pressed ball 506 in engagement with the bar in a groove 508 in the bar. This ball further cooperates with a groove 510 in the bar to maintain the latter in its normal rearward position. The bar is not affected by the movement of the bell-crank lever 314 which results from depression of the treadle 290, because of the provision of a slot 512 therein along which the pin 504 is movable.

15 In the operation of the machine, the operator mounts a last and shoe on the last pin 10 at that side of the machine which is appropriate for the particular shoe, whether a right or a left, the slide 62 which carries the heel pin being located at that time substantially at the forward end of the bar 30. It will be understood that the heel pin and the toe rest will each have been properly adjusted by the means hereinbefore described in accordance with the requirements of the style and 20 size of shoe, and that the shoe support holder 10 also will have been adjusted about its axis so that the bottom of the forepart of the shoe will lie substantially parallel to the bottom face of the holdown plate 82. After thus mounting the 25 last and shoe on the last pin, the operator moves the slide 62 with the shoe toward the toe rest to the proper position indicated by the gage 132, the slide being thereafter locked against reverse movement by the detent 98. The shoe is then 30 in the position indicated by dotted lines in Figs. 2 and 6 with its forepart resting upon the lasting apron 176 supported by the toe rest pad 14. By depression of the hand lever 122 the operator next forces the shoe support upwardly through 35 the action of the wedge 162 to press the bottom of the forepart of the shoe against the holdown plate 82.

35 Thereafter the operator partially depresses the treadle 290, as a result of which the fluid pressure means is rendered effective to impart further upward movement to the shoe support and thus to press the shoe more firmly against the holdown plate, and also to stretch the lasting apron 176 upwardly at the opposite sides of the 40 shoe to conform the unlasted portion of the forepart of the upper to the contour of the last, the toe rest acting through the apron also to conform the upper to the last at the top of the forepart. While holding the treadle in its partially depressed position the operator then swings inwardly one of the levers 346 and locks it against 45 reverse movement. By such movement of the lever the arm 342 thereon, to which the forward end of one of the cables 338 is connected, is 50 carried inwardly over the shoe bottom to position

the cable relatively to the tensioned lasting apron and to wrap it in a curve about that portion of the apron which is located at the beginning of the waist portion of the shoe. Next the operator further depresses the treadle 290 to pull downwardly thereby on the rear ends of the two cables 338, as a result of which that cable which is effective on the lasting apron is drawn forcibly inward over the shoe bottom. In response to the pull of the cable thereon the arm 342 is swung farther inwardly and somewhat forwardly toward the toe end of the shoe. When the lasting apron in this operation has been crowded or wedged by the cable somewhat inwardly between the shoe bottom and the abutment plate 134 so as to insure 15 against loss of control of the upper, as indicated in Fig. 13, the force applied to the treadle becomes great enough to overcome the resistance of the springs 392, whereupon the upwardly extending arms of the bracket 318 at the rear end of the 20 treadle swing forwardly and cause the fluid pressure means to release the lasting apron, so that the portions of the apron which are above the cables 338 are lowered, as indicated in Fig. 14. As further indicated in that figure, the cable which 25 is acting on the apron is pulled farther inwardly over the shoe bottom as the upward pull on the apron is thus relieved, thus completing the laying of the margin of the upper over the insole into position to adhere to the insole, the pressure of the apron on the margin of the upper being increased by the deflecting action of the plate 134. At this stage in the operation the operator permits the treadle 290 to rise far enough to cause the bracket 318 to be swung back to its 30 normal position by the springs 392, as a result of which the fluid pressure means is again rendered effective to pull upwardly on the lasting apron. The operator then unlocks the lever 346 which he had previously swung inwardly and returns it to 40 its idle position, the cable being withdrawn from over the shoe bottom. Thereafter the same operations are performed by use of the cable 338 at the other side of the shoe, thus completing the 45 lasting of the forepart of the shoe. The operator then completely releases the treadle 290, thus rendering the fluid pressure means no longer effective to pull upwardly on the lasting apron or to force the shoe support upwardly.

50 By lifting the hand lever 122 the operator next causes the shoe support to be lowered far enough to carry the shoe out of engagement with the holdown plate 82. By means of the handle 150 he then swings the ironing means forwardly into 55 position over the bottom of the forepart of the shoe, and thereafter depresses the hand lever 122 again to force the shoe upwardly against the ironing plates 434. By forward movement of the bar 502 he next causes the fluid pressure means to force the shoe support again upward and thereby to press the shoe forcibly against the ironing plates. As a result of such upward movement of the shoe the two ironing units move inwardly toward each other with a wiping action on the margin of the upper throughout 60 the length of the forepart of the shoe bottom the ironing plates 434 yielding upwardly, as illustrated in Fig. 19 and also conforming themselves to the contour of the shoe bottom. By such upward yield of the plates the groups of 65 balls 466 which overlie the plates are caused to fill the recesses 468 in the holders 430 and to become fixed relatively to the holders so as to 70 serve as positive means to transmit pressure from the holders to the plates, the holders at 75

this time having arrived in positions in which they are positively engaged by the casting 424 on which they are mounted. Accordingly a substantial increase in the pressure on the margin 5 of the upper is effected at the end of the ironing operation. By the action of the pressure and the heat the overlasted margin of the forepart of the upper, including the margin of the toe portion, is pressed smoothly and firmly upon the insole without objectionable wrinkles, and the heat furthermore tends to accelerate the setting of the cement whereby the upper operated upon by the lasting means is secured to the insole. The inward wiping action of the ironing means on the margin of this portion of the upper further tends to tighten the upper over the edge of the insole.

While the shoe is thus maintained under pressure of the ironing means the operator may perform the same operations described on another shoe by use of the other half of the twin machine, and after that shoe has been forced against the ironing means at that side of the machine he will release the shoe previously operated upon by first moving the bar 502 rearwardly to render the fluid pressure means no longer effective on the shoe support and by then lifting the hand lever 122. The ironing means first used will then be swung rearwardly to its idle position, carrying the ironing plates again into contact with the heater 474. It will be understood that any danger of subjecting the shoe to excessive heat by too long a contact with the ironing means is obviated by reason of the fact that when the ironing means is in contact with the shoe it is removed from the source of heat.

The shoe shown in Fig. 20 to illustrate the character of the work performed by the machine is one in which the toe end of the upper is secured adhesively to the insole and in which the upper along the shank portion of the shoe is secured by staples driven and anchored in the insole in the manner disclosed in Letters Patent No. 1,815,296, granted on July 21, 1931 upon an application of George Goddu. It is to be understood, however, that the machine is not limited to use on a shoe previously operated upon in that particular way.

Having described the invention, what I claim as new and desire to secure by Letters Patent of the United States is:

1. In a machine for operating on shoes, the combination with a shoe support, of lasting means for working the upper of a shoe on said support into lasted position with the margin of the upper lying over an insole, and a device for pressing the margin of the upper upon the insole, said device and the shoe support being mounted for relative movement in a predetermined path parallel to a plane extending generally lengthwise and heightwise of the shoe to position the device opposite the bottom of the shoe after the operation of the lasting means on the shoe.

2. In a machine for operating on shoes, the combination with a shoe support, of lasting means for working the upper of a shoe on said support into lasted position with the margin of the upper lying over an insole, and a device for pressing the margin of the upper upon the insole, said device and the shoe support being mounted for relative movement about an axis extending laterally of the shoe to position the device opposite the bottom of the shoe after the operation of the lasting means on the shoe.

3. In a machine for operating on shoes, the

combination with a shoe support arranged to support a shoe bottom upward, of lasting means for working the upper of a shoe on said support into lasted position with the margin of the upper extending inwardly over an insole, and a device for pressing the margin of the upper upon the insole, said device being mounted for swinging movement about an axis lower than the shoe into a position over the shoe bottom after the operation of the lasting means on the shoe.

4. In a machine for operating on shoes, the combination with a shoe support arranged to support a shoe bottom upward with its toe end pointing toward the rear of the machine, of lasting means for working the upper of a shoe on said support into lasted position with the margin of the upper extending inwardly over an insole, and a device for pressing the margin of the upper upon the insole, said device being arranged to occupy a position nearer the rear of the machine than the shoe in the lasting operation and being mounted for movement thereafter forwardly to a position over the bottom of the shoe.

5. In a machine for operating on shoes, the combination with a shoe support, of means for laying the margin of the upper of a shoe on said support inwardly over an insole in position to be secured to the insole by an adhesive, and a device for applying pressure and heat to the margin of the upper on the insole, said device and the shoe support being relatively movable about an axis extending laterally of the shoe to position the device opposite the bottom of the shoe after the laying of the margin of the upper over the insole.

6. In a machine for operating on shoes, the combination with a shoe support arranged to support a shoe bottom upward with its toe end pointing toward the rear of the machine, of means for laying the margin of the upper of a shoe on said support inwardly over an insole in position to be secured to the insole by an adhesive, and a device for applying pressure and heat to the margin of the upper on the insole, said device being arranged to occupy a position nearer the rear of the machine than the shoe during the operation of laying the margin of the upper over the insole and being mounted for movement thereafter forwardly to a position over the bottom of the shoe.

7. In a machine for operating on shoes, the combination with a shoe support, of lasting means for working the upper of a shoe on said support into lasted position with the margin of the upper lying over an insole, a device for pressing the margin of the upper upon the insole, said device being movable from an idle position to a position over the bottom of the shoe after the operation of said lasting means on the shoe, and a hold-down carried by said pressing device and arranged to engage the bottom of the shoe to control it in the lasting operation while said device is in its idle position and thereafter to be displaced by the movement of the device to its position over the shoe bottom.

8. In a machine for operating on shoes, the combination with a shoe support, of lasting means for working the upper of a shoe on said support into lasted position with the margin of the upper lying over an insole, a device arranged to press the margin of the upper upon the insole and so mounted as to permit it to tip about an axis extending laterally of the shoe in response to pressure of the shoe thereon to conform to the contour of the shoe bottom, said device being movable lengthwise of the shoe from an idle position to a position over the shoe bottom, a hold-

- down carried by said device and arranged to engage the bottom of the shoe when the device is in its idle position to control the shoe in the lasting operation and thereafter to be displaced by the 5 movement of the device into position over the shoe bottom, and means for limiting the tipping movement of said device when it is in its idle position to support the holdown against the pressure of the shoe thereon.
10. 9. In a machine for operating on shoes, the combination with a shoe support, of lasting means for working the upper of a shoe on said support into lasted position with the margin of the upper lying over an insole, a device for applying pressure and heat to the margin of the upper on the insole, said device and the shoe support being mounted for relative movement in a predetermined path to position the device opposite the bottom of the shoe after the lasting operation, 15 and means arranged to heat said device prior to such relative movement and to be rendered inoperative to apply heat thereto by said relative movement.
10. In a machine for operating on shoes, the combination with a shoe support, of lasting means for working the upper of a shoe on said support into lasted position with the margin of the upper lying over an insole, a device for applying pressure and heat to the margin of the upper on the insole, said device being mounted for movement in a predetermined path from an idle position to a position opposite the bottom of the shoe after the lasting operation, and a heater arranged to heat said device when it is in its idle position and 20 away from which the device is carried by its movement into position opposite the shoe bottom.
11. In a machine for operating on shoes, the combination with a shoe support, of lasting means for working the upper of a shoe on said support into lasted position with the margin of the upper lying over an insole, a device for applying pressure and heat to the margin of the upper on the insole, said device being mounted for movement from an idle position to a position opposite the 25 bottom of the shoe after the lasting operation, a heater arranged to heat said device when it is in its idle position and away from which the device is carried by its movement into position opposite the shoe bottom, and means for maintaining said device and the heater yieldingly in contact with each other when the device is in its idle position.
12. In a machine for operating on shoes, the combination with a shoe support, of lasting means for working the upper of a shoe on said support into lasted position with the margin of the upper extending inwardly over an insole, and means arranged to operate on the shoe while on said support to apply pressure and heat to the margin 30 of the upper with a wiping action thereon directed inwardly from the opposite side edges of the insole after the operation of said lasting means on the shoe.
13. In a machine for operating on shoes, the combination with a shoe support, of lasting means for working the upper of a shoe on said support into lasted position with the margin of the upper extending inwardly over an insole, and a heated ironing device comprising members arranged respectively to engage the margin of the upper at the opposite sides of the shoe bottom while the shoe is on said support and movable inwardly over the shoe bottom with a wiping action on the margin of the upper after the operation of 35 said lasting means on the shoe.
14. In a machine for operating on shoes, the combination with a shoe support, of lasting means for working the upper of a shoe on said support into lasted position with the margin of the upper extending inwardly over an insole, and a heated ironing device mounted for movement from an idle position to a position opposite the bottom of the shoe after the operation of said lasting means on the shoe, said ironing device comprising heated members movable simultaneously in directions inwardly from the opposite side edges of the insole with a wiping action on the margin of the upper. 40
15. In a machine for operating on shoes, the combination with a shoe support, of lasting means constructed and arranged to operate at the sides of the forepart of a shoe on said support the toe-end portion of which has previously been lasted to complete the lasting of the forepart from the toe-end portion rearwardly while laying the margin of the upper in these locations inwardly over an insole, and means arranged to apply pressure and heat to the overlaid margin of the upper after the operation of said lasting means thereon and while the shoe is on said support. 45
16. In a machine for operating on shoes, the combination with a shoe support, of lasting means constructed and arranged to operate at the sides of the forepart of a shoe on said support the toe-end portion of which has previously been lasted to complete the lasting of the forepart from the toe-end portion rearwardly while laying the margin of the upper in these locations inwardly over an insole, and a device constructed and arranged relatively to said lasting means to apply pressure and heat to the margin of the upper substantially throughout the length of the forepart of the shoe including the toe-end portion after the operation of said lasting means on the shoe and while 50 the shoe is on said support.
17. In a machine for operating on shoes, the combination with a shoe support, of lasting means constructed and arranged to operate at the sides of the forepart of a shoe on said support the toe-end portion of which has previously been lasted to complete the lasting of the forepart from the toe-end portion rearwardly while laying the margin of the upper in these locations inwardly over an insole, and means arranged to apply pressure and heat to the overlaid margin of the upper after the operation of said lasting means thereon, said pressing means comprising heated members movable respectively in directions inwardly from the opposite side edges of the insole in wiping contact with the margin of the upper. 55
18. In a machine for operating on shoes, the combination with a shoe support, of lasting means constructed and arranged to operate at the sides of the forepart of a shoe on said support the toe-end portion of which has previously been lasted to complete the lasting of the forepart from the toe-end portion rearwardly while laying the margin of the upper in these locations inwardly over an insole, and an ironing device constructed and arranged to apply pressure and heat to the margin of the upper substantially throughout the length of the forepart of the shoe including the toe-end portion after the operation of said lasting means 60 on the shoe, said ironing device comprising members movable respectively in directions inwardly from the opposite side edges of the insole in wiping contact with the margin of the upper. 65
19. In a machine for operating on shoes, the 70

combination with a shoe support, of lasting means constructed and arranged to operate at the sides of the forepart of a shoe on said support the toe-end portion of which has previously been lasted to complete the lasting of the forepart from the toe-end portion rearwardly while laying the margin of the upper in these locations inwardly over an insole, and an ironing device mounted for movement from an idle position to a position opposite the bottom of the forepart of the shoe after the operation of said lasting means on the shoe and arranged to apply pressure and heat to the overlaid margin of the upper.

20. In a machine for operating on shoes, the combination with a shoe support, of lasting means comprising a flexible apron for conforming the upper of a shoe on said support to the contour of a last and for laying the margin of the upper inwardly over an insole on the last into position to be secured to the insole by an adhesive, and means arranged to apply pressure and heat to the margin of the upper after the operation of said lasting means thereon and while the shoe is on said support.

21. In a machine for operating on shoes, the combination with a shoe support, of lasting means comprising a flexible apron for conforming the upper of a shoe on said support to the contour of a last and for laying the margin of the upper inwardly over an insole on the last into position to be secured to the insole by an adhesive, and a device mounted for movement from an idle position to a position opposite the bottom of the shoe after the operation of said lasting means on the shoe and constructed and arranged to press the overlaid margin of the upper upon the insole and to apply heat thereto.

22. In a machine for operating on shoes, the combination with a shoe support, of lasting means comprising a flexible apron for conforming the upper of a shoe on said support to the contour of a last and for laying the margin of the upper inwardly over an insole on the last into position to be secured to the insole by an adhesive, and an ironing device constructed and arranged to apply pressure and heat to the overlaid margin of the upper after the operation of said lasting means thereon, said ironing device comprising members movable respectively in directions inwardly from the opposite side edges of the insole in wiping contact with the upper.

23. In a machine for operating on shoes, the combination with a shoe support, of lasting means constructed and arranged to operate at the forepart of a shoe on said support the toe-end portion of which has previously been lasted to complete the lasting of the forepart from the toe-end portion rearwardly, said lasting means comprising a flexible apron for conforming the upper to the contour of a last and for laying the margin of the upper inwardly over an insole on the last into position to be secured to the insole by an adhesive, and an ironing device constructed and arranged to apply pressure and heat to the margin of the upper substantially throughout the length of the forepart of the shoe including the toe-end portion after the operation of said lasting means on the shoe and while the shoe is on said shoe support.

24. In a machine for operating on shoes, the combination with a shoe support, of lasting means for working the upper of a shoe on said support into lasted position with the margin of the upper lying over an insole, a device for applying pressure and heat to the margin of the upper

on the insole after the lasting operation, a hold-down for engaging the bottom of the shoe in the lasting operation, and power means for effecting relative movement of said shoe support and hold-down to control the shoe in the lasting 5 operation and for thereafter effecting relative movement of the shoe support and said pressing device to press the shoe.

25. In a machine for operating on shoes, the combination with a shoe support, of lasting 10 means for working the upper of a shoe on said support into lasted position with the margin of the upper lying over an insole, a device for applying pressure and heat to the margin of the upper on the insole after the lasting operation, a hold-down for engaging the bottom of the shoe in the lasting operation, and means for moving the shoe support to force the shoe against the hold-down for the lasting operation and for thereafter moving said support to force the shoe against said 15 20 pressing device.

26. In a machine for operating on shoes, the combination with a shoe support, of lasting means for working the upper of a shoe on said support into lasted position with the margin of the upper lying over an insole, a device for applying pressure to the margin of the upper on the insole after the lasting operation, a hold-down for engaging the bottom of the shoe in the lasting operation, and fluid pressure means 25 constructed and arranged to move the shoe support to force the shoe against the hold-down for the lasting operation and thereafter to move the shoe support to force the shoe against the pressing 30 35 device.

27. In a machine for operating on shoes, the combination with a shoe support, of lasting means arranged to operate upon a shoe on said support, a hold-down for engaging the bottom of the shoe in the lasting operation, fluid pressure mechanisms arranged respectively to operate said lasting means and to operate the shoe support to force the shoe against the hold-down, a member movable by the operator to render both said fluid pressure mechanisms operative, a device movable into a position opposite the shoe bottom after the lasting operation for applying pressure to the margin of the upper, and an additional member movable by the operator for controlling one of said fluid pressure mechanisms independently 40 45 50 of the other to cause said mechanism to operate the shoe support to force the shoe against said pressing device.

28. In a machine for operating on shoes, a flexible apron for conforming an upper to the contour of a last, and means constructed to conform itself to the contour of the shoe bottom and to act through said apron to lay the margin of the upper inwardly over the shoe bottom.

29. In a machine for operating on shoes, a flexible apron for conforming an upper to the contour of a last, and a flexible member arranged to act through said apron by pressure thereon along and adjacent to the edge of the shoe bottom to lay the margin of the upper inwardly 60 65 over the shoe bottom.

30. In a machine for operating on shoes, a flexible apron for conforming an upper to the contour of a last, and a flexible cable arranged to extend lengthwise along the edge of the shoe bottom and to act through said apron to lay the margin of the upper inwardly over the shoe bottom in response to a pull applied to said cable.

31. In a machine for operating on shoes, a 70 75

- flexible elastic apron for conforming an upper to the contour of a last, a flexible cable arranged to extend lengthwise along the edge of the shoe bottom and to act through said apron to lay the margin of the upper inwardly over the shoe bottom in response to a pull applied to said cable, and a coil spring surrounding said cable and arranged to engage said apron.
32. In a machine for operating on shoes, a flexible apron for conforming an upper to the contour of a last, a flexible cable arranged to extend lengthwise along the edge of the shoe bottom and to act through said apron to lay the margin of the upper inwardly over the shoe bottom in response to a pull applied to said cable, and a member mounted on said cable for engaging the apron and arranged to turn about the cable in response to frictional action of the apron thereon.
33. In a machine for operating on shoes, a flexible apron for conforming an upper to the contour of a last, a flexible cable arranged to extend lengthwise along the edge of the shoe bottom and to act through said apron to lay the margin of the upper inwardly over the shoe bottom in response to a pull applied to said cable, and a member surrounding said cable for engaging the apron and relatively to which the cable is movable lengthwise in laying the upper over the insole.
34. In a machine for operating on shoes, a flexible apron and means for pulling it heightwise of a last to conform an upper to the contour of the last, means arranged to act through said apron to lay the margin of the upper inwardly over the bottom of the last, and means for relaxing the force of the pull applied to said apron as the margin of the upper is thus laid inwardly.
35. In a machine for operating on shoes, a flexible elastic apron and means for stretching it to conform an upper to the contour of a last, a flexible cable arranged to extend lengthwise along the edge of the shoe bottom and to act through said apron to lay the margin of the upper inwardly over the shoe bottom, and means for relaxing the stretching force applied to said apron to facilitate the action of said cable on the apron.
36. In a machine for operating on shoes, a flexible lasting apron, means for pulling said apron heightwise of a last to conform an upper to the contour of the last, means arranged to act through said apron to lay the margin of the upper inwardly over the bottom of the last, a member for operating said last-named means, and mechanism controlled by said member for relaxing the force of the pull applied to said apron.
37. In a machine for operating on shoes, a flexible lasting apron, power means for pulling said apron heightwise of a last to conform an upper to the contour of the last, means arranged to act through said apron to lay the margin of the upper inwardly over the bottom of the last, a member for operating said last-named means, and mechanism operative in response to force applied to said member to cause said power means to relax the force of the pull on said apron.
38. In a machine for operating on shoes, a flexible elastic apron, power means for stretching said apron to conform an upper to the contour of a last, a flexible cable arranged to extend lengthwise along the edge of the shoe bottom
- and to act through said apron to lay the margin of the upper inwardly over the shoe bottom, a member for pulling said cable to operate it, and mechanism operative in response to force applied to said member to cause said power means to relax the stretching force applied to said apron.
39. In a machine for operating on shoes, a flexible elastic apron, fluid pressure means for applying a pull to said apron to conform an upper to the contour of a last, a flexible cable arranged to extend lengthwise along the edge of the shoe bottom and to act through said apron to lay the margin of the upper inwardly over the shoe bottom, a member movable by the operator to operate said cable, connections between said member and the cable comprising parts relatively movable in response to force applied to said member, and mechanism arranged to be operated by the relative movement of said parts to cause said fluid pressure means to relax the force of the pull on the apron.
40. In a machine for operating on shoes, a flexible elastic apron, fluid pressure means for pulling said apron heightwise of a last to conform an upper to the contour of the last, a flexible cable arranged to extend lengthwise along the edge of the shoe bottom and to act through said apron to lay the margin of the upper inwardly over the shoe bottom, a member movable to operate said cable, and valve mechanism controlled by said member to cause said fluid pressure means to pull the apron in response to an initial movement of said member and thereafter to cause said means to relax the force of the pull on the apron in response to further movement of said member as the cable is operated.
41. In a machine for operating on shoes, a flexible elastic apron, fluid pressure means for pulling said apron heightwise of a last to conform an upper to the contour of the last, means arranged to act through said apron to lay the margin of the upper inwardly over the bottom of the last, and valve mechanism movable to cause said fluid pressure means to relax the force of the pull on the apron to facilitate the laying of the margin of the upper inwardly.
42. In a machine for operating on shoes, the combination with a support for a last and shoe, of lasting means arranged to conform the shoe upper to the contour of the last and movable inwardly over the bottom of the last to lay the margin of the upper over an insole on the last, and a device located opposite the bottom of the last and relatively to which said lasting means is thus inwardly movable, said device being arranged to act as a deflector on said means in its inward movement to increase its pressure on the margin of the upper.
43. In a machine for operating on shoes, the combination with a support for a last and shoe, of lasting means comprising a flexible cable arranged to extend lengthwise along the edge of the shoe bottom and movable to lay the margin of the upper inwardly over the shoe bottom, and a member opposite the shoe bottom arranged to act as a deflector on said cable to force the cable toward the shoe bottom in its inward movement.
44. In a machine for operating on shoes, the combination with a support for a last and shoe, of a flexible apron for conforming the shoe upper to the contour of the last, means arranged to act through said apron to lay the margin of the upper inwardly over the shoe bottom, and a member opposite the shoe bottom relatively to which said

means is movable inwardly over the shoe bottom, said member being arranged to act on the apron to increase its pressure on the margin of the upper as the apron is forced inwardly over the shoe bottom by said means.

45. In a machine for operating on shoes, the combination with a support for a last and shoe, of a flexible rubber apron for conforming the shoe upper to the contour of the last, means arranged to act through said apron to lay the margin of the upper inwardly over the shoe bottom, and an abutment arranged to provide a space between it and the shoe bottom into which the apron is wedged by said means to increase the pressure of the apron on the margin of the upper.

46. In a machine for operating on shoes, the combination with a support for a last and shoe, of a flexible rubber apron for conforming the shoe upper to the contour of the last, a flexible cable arranged to extend lengthwise along the edge of the shoe bottom and to act through said apron to lay the margin of the upper inwardly over the shoe bottom, and an abutment arranged to provide a space between it and the shoe bottom into which the apron is wedged by said cable to increase the pressure of the apron and the cable on the margin of the upper.

47. In a machine for operating on shoes, the combination with a support for a last and shoe, of a flexible apron and means for pulling it heightwise of the last to conform the shoe upper to the contour of the last, means arranged to act through said apron to lay the margin of the upper inwardly over the shoe bottom, an abutment arranged to provide a space between it and the shoe bottom into which the apron is wedged in laying the margin of the upper inwardly, and means for relaxing the force of the pull on said apron after the apron has been partially wedged into said space.

48. In a machine for operating on shoes, the combination with a support for a last and shoe, of a flexible rubber lasting apron, fluid pressure means for pulling said apron heightwise of the last to conform the shoe upper to the contour of the last, a flexible cable arranged to extend lengthwise along the edge of the shoe bottom and to act through said apron to lay the margin of the upper inwardly over the shoe bottom, an abutment arranged to provide a space between it and the shoe bottom into which the apron is wedged by the cable, a member for operating said cable, and mechanism operative in response to force applied to said member to cause said fluid pressure means to relax the force of the pull on the apron after the apron has been partially wedged into said space.

49. In a machine for operating on shoes, a flexible apron and means for pulling it heightwise of a last to conform an upper to the contour of the last along a side of the last, a flexible cable arranged to extend lengthwise along the edge at the shoe bottom and to act through said apron to lay the margin of the upper inwardly over the shoe bottom, means for imparting to the cable an inward positioning movement while the apron is under tension, and additional means arranged to act thereafter on said cable to lay the margin of the upper inwardly.

50. In a machine for operating on shoes, a flexible apron and means for pulling it heightwise of a last to conform an upper to the contour of the last along a side of the last, a flexible cable arranged to extend lengthwise along the edge of the shoe bottom and to act through said apron to

lay the margin of the upper inwardly over the shoe bottom, a member connected to one end of said cable and movable widthwise of the last to impart to the cable an inward positioning movement while the apron is under tension, and means for thereafter applying a pull to the other end of the cable to lay the margin of the upper inwardly.

51. In a machine for operating on shoes, a flexible apron and means for pulling it heightwise of a last to conform an upper to the contour of the last along a side of the last, a flexible cable arranged to extend lengthwise along the edge of the shoe bottom and to act through said apron to lay the margin of the upper inwardly over the shoe bottom, a lever connected to one end of said cable and movable widthwise of the last to impart to the cable an inward positioning movement while the apron is under tension, means for locking said lever against reverse movement, and means for thereafter applying a pull to said cable to lay the margin of the upper inwardly.

52. In a machine for operating on shoes, a flexible apron and means for pulling it heightwise of a last to conform an upper to the contour of the last along a side of the last, a flexible cable arranged to extend lengthwise along the edge of the shoe bottom and to act through said apron to lay the margin of the upper inwardly over the shoe bottom, manually operated means for imparting to the cable an inward positioning movement while the apron is under tension, and a treadle for thereafter applying a pull to the cable to lay the margin of the upper inwardly.

53. In a machine for operating on shoes, a flexible apron arranged to extend heightwise of a last for conforming an upper to the contour of the last along a side of the last, a flexible cable arranged to extend lengthwise along the edge of the shoe bottom and to act through said apron to lay the margin of the upper inwardly over the shoe bottom, means for applying a pull to said cable to lay the margin of the upper inwardly, and a member supporting one end of said cable and mounted for swinging movement laterally of the shoe in response to the pull of the cable thereon.

54. In a machine for operating on shoes, a flexible apron arranged to extend heightwise of a last for conforming an upper to the contour of the forepart of the last along a side of the forepart, a flexible cable arranged to extend lengthwise along the edge of the shoe bottom and to act through said apron to lay the margin of the upper inwardly over the shoe bottom, means for bending the cable inwardly over the shoe bottom about a portion of the apron located in the vicinity of the waist portion of the shoe, and means for thereafter applying to that portion of the cable which acts on the apron a pull directed toward the toe end of the shoe and laterally of the shoe for laying the margin of the upper inwardly.

55. In a machine for operating on shoes, a flexible apron arranged to extend heightwise of a last for conforming an upper to the contour of the forepart of the last along a side of the forepart, a flexible cable arranged to extend lengthwise along the edge of the shoe bottom and to act through said apron to lay the margin of the upper inwardly over the shoe bottom, an arm supporting one end of said cable and arranged to extend inwardly over the shoe bottom to bend the cable about a portion of the apron located in the vicinity of the waist portion of the shoe, and means for applying to that portion of the cable which acts on the apron a pull directed toward the

toe end of the shoe and laterally of the shoe for laying the margin of the upper inwardly, said arm being yieldingly movable in response to the pull of the cable thereon.

- 5 56. In a machine for operating on shoes, a flexible lasting apron arranged to embrace the forepart of a shoe and last and to extend heightwise of the last at the opposite sides of the forepart to conform the shoe upper to the contour of the last, flexible cables arranged to extend lengthwise of the edge of the shoe bottom along the opposite sides of the forepart and to act through said apron to lay the margin of the upper inwardly over the shoe bottom, said cables being crossed and extending lengthwise and laterally of the shoe beyond the toe end of the shoe, and means for pulling on each cable in a location beyond the point where it crosses the other cable for operating it.
- 10 57. In a machine for operating on shoes, a flexible lasting apron arranged to embrace the forepart of a shoe and last and to extend heightwise of the last at the opposite sides of the forepart to conform the shoe upper to the contour of the last, flexible cables arranged to extend lengthwise of the edge of the shoe bottom along the opposite sides of the forepart and to act through said apron to lay the margin of the upper inwardly over the shoe bottom, said cables being crossed and extending lengthwise and laterally of the shoe beyond the toe end of the shoe, means for operating each cable by a pull in a direction toward the toe end of the shoe on that portion of the cable which acts on the apron, and an arm supporting each cable in a location near a portion of the apron which is in the vicinity of the waist portion of the shoe, said arm being yieldingly movable laterally of the shoe and toward its toe-end in response to pull of the cable thereon.
- 15 58. In a machine for operating on shoes, the combination with a support for a shoe and last, of a flexible apron for conforming the shoe upper to the contour of the last, devices arranged to act through said apron at the opposite sides of the shoe respectively to lay the margin of the upper inwardly over the bottom of the last, and means for operating said devices successively to lay the margin of the upper inwardly first at one side of the shoe bottom and then at the other side of the shoe bottom.
- 20 59. In a machine for operating on shoes, the combination with a support for a shoe and last, of a flexible apron for conforming the shoe upper to the contour of the last, flexible cables arranged to extend lengthwise along the edge of the shoe bottom and to act through said apron respectively at the opposite sides of the shoe to lay the margin of the upper inwardly over the bottom of the last, means for carrying first one of the cables and then the other cable inwardly to position it relatively to said apron, and means for applying a pull to the first cable to lay the margin of the upper over the last bottom before the other cable is carried inwardly and for thereafter similarly operating the other cable after it has been carried inwardly.
- 25 60. In a machine for operating on shoes, the combination with a shoe support, of lasting means arranged to operate upon a shoe on said support, a holddown for engaging the bottom of the shoe in the lasting operation, power means for effecting relative movement of said shoe support and holddown to cause the holddown to press firmly on the shoe, a member movable by the operator to render said power means operative, and connections between said member and the lasting means for

operating the lasting means by the movement of said member.

61. In a machine for operating on shoes, the combination with a shoe support, of lasting means arranged to operate upon a shoe on said support, a member movable by the operator to operate said lasting means, a holddown for engaging the bottom of the shoe in the lasting operation, fluid pressure means for effecting relative movement of said shoe support and holddown to cause the holddown to press firmly on the shoe, and valve mechanism controlled by said member for rendering said fluid pressure means operative.

62. In a machine for operating on shoes, the combination with a support for a shoe and last, of a holddown for engaging the bottom of the shoe, a flexible apron for conforming the shoe upper to the contour of the last, a flexible cable arranged to extend lengthwise along the edge of the shoe bottom and to operate through said apron to lay the margin of the upper inwardly over the bottom of the last, a member movable by the operator to operate said cable, fluid pressure means for effecting relative movement of said shoe support and holddown to cause the holddown to press firmly on the shoe, and valve mechanism controlled by said member for rendering said fluid pressure means operative.

63. In a machine for operating on shoes, the combination with a shoe support, of lasting means arranged to operate upon a shoe on said support, a holddown for engaging the bottom of the shoe in the lasting operation, fluid pressure mechanisms arranged respectively to operate said lasting means and to effect relative movement of said shoe support and holddown to cause the holddown to press firmly on the shoe, valve mechanisms associated respectively with said fluid pressure mechanisms, and means for controlling said valve mechanisms.

64. In a machine for operating on shoes, the combination with a support for a shoe and last, of a holddown for engaging the bottom of the shoe, a flexible apron for conforming the shoe upper to the contour of the last, a device arranged to act through said apron to lay the margin of the upper inwardly over the shoe bottom, a member movable by the operator to operate said device, fluid pressure mechanisms arranged respectively to apply a pull to said apron and to operate the shoe support to force the shoe against the holddown, and means controlled by said member for rendering said fluid pressure mechanisms operative.

65. In a machine for operating on shoes, the combination with a support for a shoe and last, of a flexible apron for conforming the shoe upper to the contour of the last, a device arranged to act through said apron to lay the margin of the upper inwardly over the bottom of the last, a member movable by the operator to operate said device, and power means controlled by said member for applying a pull to said apron.

66. In a machine for operating on shoes, the combination with a support for a shoe and last, of a flexible apron for conforming the shoe upper to the contour of the last, fluid pressure mechanism for applying a pull to said apron, a device arranged to act through said apron to lay the margin of the upper inwardly over the bottom of the last, and a member movable by the operator to render said fluid pressure mechanism operative and further movable to operate said device.

67. In a machine for operating on shoes, the combination with a support for a shoe and last, of a flexible apron for conforming the shoe upper to

- the contour of the last, a cable arranged to extend lengthwise along the edge of the shoe bottom and to act through said apron to lay the margin of the upper inwardly over the shoe bottom, 5 a member for operating said cable, fluid pressure mechanism for applying a pull to said apron, and valve mechanism controlled by said member for rendering said fluid pressure mechanism operative.
- 10 68. In a machine for operating on shoes, the combination with a support for a shoe and last, of a flexible apron for conforming the shoe upper to the contour of the last, power means for applying a pull to said apron, a device arranged to act 15 through said apron to lay the margin of the upper inwardly over the bottom of the last, and means movable by the operator to operate said device.
- 15 69. In a machine for operating on shoes, the combination with a support for a shoe and last, 20 of a flexible apron for conforming the shoe upper to the contour of the last, fluid pressure means for applying a pull to said apron, valve mechanism for controlling said fluid pressure means, and means movable by the operator and arranged 25 to act through said apron to lay the margin of the upper inwardly over the bottom of the last.
70. In a machine for operating on shoes, the combination with a shoe support, of lasting means arranged to operate on a shoe on said support, 30 fluid pressure mechanism comprising members relatively movable in response to pressure of fluid against them to operate said lasting means, a reservoir for fluid, a continuously operating pump for supplying fluid from said reservoir under pressure to said mechanism, means for admitting the fluid intermittently to said mechanism, means providing a by-pass for the fluid from the pump to said reservoir, and a pressure control valve arranged to permit escape of fluid 35 through said by-pass whenever a predetermined pressure of the fluid is attained either when said mechanism is in operation or when it is idle.
71. In a machine for operating on shoes, the combination with a shoe support, of lasting means arranged to operate on a shoe on said support, 40 fluid pressure mechanism comprising members relatively movable in response to pressure of fluid against them to operate said lasting means, a reservoir for fluid, a continuously operating pump for drawing fluid from said reservoir and for supplying it under pressure to said mechanism, means for admitting the fluid intermittently to 45 said mechanism, and a spring-controlled relief valve located between the pump and said fluid pressure mechanism and arranged to open and return the fluid to said reservoir whenever a predetermined pressure of the fluid is attained.
72. In a machine for operating on shoes, the combination with a support for a shoe and last, 50 of a flexible elastic apron for conforming the shoe upper to the contour of the last, fluid pressure mechanism for stretching said apron, and means for supplying fluid under pressure to said mechanism, said fluid pressure mechanism being movable in response to pressure of the fluid thereon until the resistance of the apron causes it to come to a stop.
73. In a machine for operating on shoes, a 55 flexible apron arranged to embrace the forepart of an upper on a last for conforming the upper to the contour of the last, means for pulling said apron heightwise of the last at the opposite sides of the last, and a shoe rest constructed and arranged to act through said apron substantially 60 throughout the width of the last to press the upper against the top of the forepart of the last.
74. In a machine for operating on shoes, a 65 flexible rubber apron arranged to embrace the forepart of an upper on a last for conforming the upper at the rear of the toe portion to the contour of the last, means for pulling said apron heightwise of the last at the opposite sides of the last, and a shoe rest arranged to engage said apron in a location opposite the top of the forepart of the last at the rear of the toe portion and to act through the apron to press the upper against the last substantially throughout the width of the last.
75. In a machine for operating on shoes, a 70 flexible apron arranged to embrace the forepart of an upper on a last for conforming the upper to the contour of the last, means for pulling said apron heightwise of the last at the opposite sides of the last, a shoe rest arranged to act through said apron to press the upper against the top of the forepart of the last, and means for anchoring said apron to the shoe rest to prevent it from shifting relatively to the shoe rest.
76. In a machine for operating on shoes, a 75 flexible apron arranged to embrace the forepart of an upper on a last for conforming the upper to the contour of the last, means for pulling said apron heightwise of the last at the opposite sides of the last, and a shoe rest arranged to act through said apron to press the upper against the top of the forepart of the last, said apron having a projection thereon arranged to enter a recess in the shoe rest to prevent it from shifting relatively to the shoe rest.
77. In a machine for operating on shoes, the combination with means for operating on shoe materials on a last, of a support for the shoe and last, a holdown for engaging the bottom of the shoe, and fluid pressure mechanism for effecting 40 relative movement of said shoe support and holdown to cause the holdown to press firmly on the shoe, said fluid pressure mechanism being movable in response to pressure of the fluid thereon until the resistance to said relative movement 45 causes it to come to a stop.
78. In a machine for operating on shoes, the combination with means for operating on shoe materials on a last, of a support for the shoe and last, a holdown for engaging the bottom of the 50 shoe, fluid pressure mechanism for effecting relative movement of said shoe support and holdown to cause the holdown to press firmly on the shoe, a continuously operating pump for supplying fluid under pressure to said mechanism, and a pressure-control valve arranged to permit escape of fluid by said pump whenever a predetermined pressure of the fluid is attained and thus to determine the amount of pressure applied by the holdown to the shoe.
79. In a machine for operating on shoes, the combination with means for operating on shoe materials on a last, of a support for the shoe and last, a holdown for engaging the bottom of the 55 shoe, a wedge movable by the operator to elevate the shoe support and force the shoe against the holdown, and power means for thereafter further elevating the shoe support to force the shoe more firmly against the holdown.
80. In a machine for operating on shoes, the 60 combination with means for operating on shoe materials on a last, of a support for the shoe and last, a holdown for engaging the bottom of the shoe, a member movable by the operator to elevate the shoe support and force the shoe against 65
- 75 75

the holdown, and fluid pressure mechanism for thereafter further elevating the shoe support to force the shoe more firmly against the holdown.

81. In a machine for operating on shoes, the combination with means for operating on shoe materials on a last, of a shoe rest for supporting the forepart of the shoe and last, a holdown arranged to engage the bottom of the forepart of the shoe and to occupy a position opposite the bottom of the forepart when the shoe is first positioned on said shoe rest, and a heel-end support including a last pin for engaging the heel end of the last in its spindle hole, said heel-end support being arranged to occupy a position comparatively remote from said shoe rest to receive each last and shoe and being movable with the last and shoe toward the shoe rest to position the forepart of the shoe in proper relation to the holdown and shoe rest.

82. In a machine for operating on shoes, the combination with means for operating on shoe materials on a last, of a shoe rest arranged to support the forepart of a shoe and last presented with the toe of the shoe pointing toward the rear of the machine, a holdown for engaging the bottom of the forepart of the shoe, and a heel-end support including a last pin for engaging the heel end of the last in its spindle hole, said heel-end support being arranged to occupy a position comparatively remote from said shoe rest to receive each last and shoe and being movable toward the rear of the machine with the last and shoe to position the forepart of the shoe in proper relation to the holdown and shoe rest.

83. In a machine for operating on shoes, the combination with means for operating on shoe materials on a last, of a shoe rest for supporting the forepart of the shoe and last, a holdown for engaging the bottom of the forepart of the shoe, a heel-end support including a last pin for engaging the heel end of the last in its spindle hole, said heel-end support being movable toward said shoe rest to position the forepart of the shoe in proper lengthwise relation to the holdown and shoe rest, and a member carrying said shoe rest and heel-end support and adjustable about an axis extending laterally of the shoe and located approximately at the ball of the shoe further to position the bottom of the forepart of the shoe in proper relation to the holdown.

84. In a machine for operating on shoes, the combination with a shoe support arranged to support a shoe bottom upward, of a device for applying pressure and heat to the bottom of the shoe, said device being mounted for swinging movement about an axis lower than the shoe from an idle position to a position over the bottom of the shoe prior to its engagement with the shoe.

85. In a machine for operating on shoes, the combination with a shoe support arranged to support a shoe bottom upward with its toe end pointing toward the rear of the machine, of a device for applying pressure and heat to the bottom of the shoe, said device being arranged to occupy an initial position nearer the rear of the machine than the shoe and being mounted for swinging movement about an axis extending laterally of the shoe to a position over the shoe bottom.

86. In a machine for operating on shoes, the combination with a support for a last and shoe arranged to support them bottom upward, of a device constructed for engagement with the mar-

gin of the shoe upper extending inwardly over an insole on the last substantially in lasted position for applying pressure and heat to said margin, said device being mounted for swinging movement about a substantially horizontal axis 5 from an initial position to a position over the bottom of the shoe prior to its engagement with the shoe.

87. In a machine for operating on shoes, the combination with a shoe support, of a device for applying pressure and heat to the bottom of a shoe on said support, said device being movable in a predetermined path from an initial position to a position opposite the bottom of the shoe prior to its engagement with the shoe, and means 15 for limiting such movement of the device to determine its relation to the shoe.

88. In a machine for operating on shoes, the combination with a support for a last and shoe arranged to support them bottom upward, of 20 a device constructed for engagement with the margin of the shoe upper extending inwardly over an insole on the last substantially in lasted position to apply pressure and heat to said margin, said device being mounted for movement 25 in a predetermined path from an idle position to a position over the bottom of the shoe prior to its engagement with the upper, and means for limiting such movement of the device to determine its relation to the shoe.

89. In a machine for operating on shoes, the combination with means for supporting a shoe against pressure applied on its bottom face, of a device constructed to apply pressure and heat to the bottom of the shoe after lasting but before an outsole is applied to the shoe, said device being movable in a fixed path from an idle position into position to operate on the shoe, and means for limiting such movement of the device to determine its relation to the shoe prior 40 to its engagement with the shoe.

90. In a machine for operating on shoes, the combination with means for supporting a shoe against pressure applied on its bottom face, of 45 a device for applying pressure and heat to the bottom of the shoe, said device being mounted for movement in a predetermined path from an idle position into a position opposite the shoe bottom prior to its contact with the shoe, and heating means arranged to heat said device when 50 it is in its idle position and away from the influence of which the device is carried by its movement to operating position.

91. In a machine for operating on shoes, the combination with means for supporting a shoe 55 against pressure applied on its bottom face, of a device for applying pressure and heat to the bottom of the shoe, said device being mounted for movement in a predetermined path from an idle position into a position opposite the shoe 60 bottom prior to its contact with the shoe, and a heater arranged to contact with said device for heating it when the device is in its idle position and out of contact with which the device is carried by its movement to operating position.

92. In a machine for operating on shoes, the combination with a support for a shoe and last, of a device constructed for engagement with the margin of the shoe upper extending inwardly over an insole on the last substantially in lasted position for applying pressure and heat to said margin, said device being mounted for movement from an idle position to a position opposite the bottom of the shoe prior to its engagement with the upper, and means arranged to heat said de- 75

vice when it is in its idle position and to be rendered inoperative to apply heat thereto by the movement of the device to its position opposite the shoe bottom.

5 93. In a machine for operating on shoes, the combination with a shoe support, of a device for applying pressure and heat to the bottom of a shoe on said support, said device being mounted for movement from an idle position to a position opposite the bottom of the shoe, a heater arranged to heat said device and away from which the device is carried by said movement, and spring means for holding the heater yieldingly in contact with said device prior to said movement.

10 94. In a machine for operating on shoes, the combination with a shoe support, of a device for applying pressure and heat to the bottom of a shoe on said support, means movable by the operator to effect relative movement of said device and the shoe support to cause the device to engage the shoe, and power means for thereafter effecting automatically further relative movement of said device and the shoe support to press the shoe.

15 95. In a machine for operating on shoes, the combination with a shoe support arranged to support a shoe bottom upward, of a device for applying pressure and heat to the bottom of the shoe, means movable by the operator to raise said shoe support to carry the shoe into contact with said device, and power means for thereafter further raising the shoe support to press the shoe.

20 96. In a machine for operating on shoes, the combination with a shoe support, of a device for applying pressure and heat to the bottom of a shoe on said support, means for effecting relative movement of said device and the shoe support heightwise of the shoe to engage said device with the shoe, and fluid pressure means for thereafter effecting further relative movement of said device and the shoe support to press the shoe.

25 97. In a machine for operating on shoes, the combination with a shoe support, of a device for applying pressure to the bottom of a shoe on said support, said device being movable from an idle position to a position opposite the bottom of the shoe, means movable by the operator after the device has thus been positioned opposite the bottom of the shoe to cause the device to engage the shoe, and fluid pressure means for thereafter effecting relative movement of said device and the shoe support to press the shoe.

30 98. In a machine for operating on shoes, the combination with means for supporting a shoe against pressure applied on its bottom face, of a device constructed to apply pressure and heat to the bottom of the shoe after lasting but before an outsole is applied to the shoe, fluid pressure mechanism for effecting relative movement of said device and the shoe-supporting means to press the shoe, a continuously operating pump for supplying fluid under pressure to said mechanism, and a pressure control valve arranged to permit escape of fluid supplied by said pump whenever a predetermined pressure of the fluid is attained and thus to determine the amount of pressure applied to the shoe.

35 99. In a machine for operating on shoes, the combination with a shoe support arranged to support a shoe bottom upward, of a device for applying pressure and heat to the bottom of the shoe after lasting but before an outsole is applied to the shoe, fluid pressure mechanism for elevating the shoe support to press the shoe

against said device, a continuously operating pump for supplying fluid under pressure to said mechanism, and a spring-controlled relief valve located between the pump and said mechanism and arranged to open whenever a predetermined pressure of the fluid is attained.

40 100. In a machine for operating on shoes, the combination with means for supporting a shoe against pressure applied on its bottom face, of a device for applying pressure to the bottom of the shoe after lasting but before an outsole is applied to the shoe, said device being movable from an idle position to a position opposite said shoe-supporting means prior to its engagement with the shoe and comprising means movable laterally of the shoe in wiping contact therewith at the opposite sides of the shoe bottom.

45 101. In a machine for operating on shoes, the combination with a shoe support, of a device for applying pressure to the bottom of a shoe on said support, after lasting but before an outsole is applied to the shoe, said device being movable from an idle position to a position opposite the bottom of the shoe prior to its engagement with the shoe and comprising members movable inwardly over the shoe bottom in wiping contact therewith in response to pressure of the shoe on said members.

50 102. In a machine for operating on shoes, the combination with a shoe support, of a device for applying pressure to the bottom of a shoe on said support after lasting but before an outsole is applied to the shoe, said device being movable from an idle position to a position opposite the bottom of the shoe prior to its engagement with the shoe and comprising members movable laterally of the shoe in wiping contact therewith at the opposite sides of the shoe bottom respectively, and means for heating said members.

55 103. In a machine for operating on shoes, the combination with means for supporting a shoe against pressure applied on its bottom face, of a device for applying pressure to the bottom of the shoe, said device comprising different members one supported on the other, one of said members being mounted for tipping movement about an axis extending laterally of the shoe and the other about an axis extending lengthwise of the shoe to permit the device to adjust itself to the shoe, and shoe-pressing means supported on one of said members for engaging the shoe at both sides of the shoe bottom.

60 104. In a machine for operating on shoes, the combination with means for supporting a shoe against pressure applied on its bottom face, of a device for applying pressure to the bottom of the shoe, said device comprising different members one supported on the other, one of said members being mounted for tipping movement about an axis extending laterally of the shoe and the other about an axis extending lengthwise of the shoe to permit the device to adjust itself to the shoe, shoe-pressing means supported on one of said members for engaging the shoe at both sides of the shoe bottom, and means for heating said shoe-pressing means.

65 105. In a machine for operating on shoes, the combination with means for supporting a shoe against pressure applied on its bottom face, of a device for applying pressure to the bottom of the shoe, said device comprising different members one supported on the other, one of said members being mounted for tipping movement about an axis extending laterally of the shoe and the other

- about an axis extending lengthwise of the shoe to permit the device to adjust itself to the shoe, and shoe-pressing means supported on one of said members for engaging the shoe at both sides 5 of the shoe bottom and flexibly conformable to the contour of the shoe in response to pressure of the shoe thereon.
106. In a machine for operating on shoes, the combination with means for supporting a shoe against pressure applied on its bottom face, of a device for applying pressure to the bottom of the shoe after lasting but before an outsole is applied to the shoe, said device comprising members movable inwardly toward each other in wiping contact 15 with the shoe at the opposite sides of the shoe bottom respectively and each flexibly conformable to the contour of the shoe in response to pressure of the shoe thereon, and means for heating said members.
107. In a machine for operating on shoes, the combination with means for supporting a shoe against pressure applied on its bottom face, of a device for applying pressure to the bottom of the shoe after lasting but before an outsole is applied 20 to the shoe, said device being movable from an idle position to a position opposite said shoe-supporting means prior to its engagement with the shoe and comprising members movable inwardly toward each other in wiping contact with 25 the shoe at the opposite sides of the shoe bottom respectively and each flexibly conformable to the contour of the shoe in response to pressure of the shoe thereon.
108. A device for ironing the bottoms of shoes, 30 said device comprising ironing units movable toward each other laterally of a shoe to iron the bottom of the shoe and each comprising heated shoe-engaging means flexibly conformable to the contour of the shoe in response to pressure of the shoe thereon, and a movable support common 35 to both said units.
109. A device for ironing the bottoms of shoes, said device comprising ironing units arranged to operate respectively at the opposite sides of the 40 bottom of a shoe, and means for moving said units inwardly toward each other in response to pressure of the shoe thereon, each of said units comprising shoe-engaging means flexibly conformable to the contour of the shoe.
110. A device for ironing the bottoms of shoes, 45 said device comprising ironing units arranged to operate respectively at the opposite sides of the bottom of a shoe, and means for moving said units inwardly toward each other in response to pressure of the shoe thereon, each of said units comprising a heated shoe-engaging plate flexibly 50 conformable to the contour of the shoe.
111. A shoe-pressing device having a shoe-pressing portion conformable to the contour of 55 a shoe in response to pressure of the shoe thereon, a group of loose elements backing up said shoe-pressing portion and arranged to adjust themselves in accordance with the contour of the shoe and then to support said shoe-pressing portion 60 against pressure of the shoe upon it, and a fence confining said group of elements laterally and yieldable in response to the pressure of the shoe on said shoe-pressing portion.
112. A shoe-pressing device comprising a shoe- 65 pressing member flexibly conformable to the contour of a shoe in response to pressure of the shoe thereon, a group of metal balls backing up said shoe-pressing member and arranged to adjust themselves in accordance with the contour of the shoe and then to support said shoe-pressing mem- 70 ber against pressure of the shoe upon it, and a row of pins confining said group of balls laterally and yieldable in response to the pressure of the shoe on said member.
113. A shoe-pressing device comprising a holder 5 having a recess therein, a shoe-pressing member supported by said holder and flexibly conformable to the contour of a shoe in response to pressure of the shoe thereon, a group of loose elements in said recess backing up said shoe-pressing member and 10 arranged to adjust themselves in accordance with the contour of the shoe and then to become substantially fixed relatively to the holder by contact with one another and with the holder, and means on the holder confining said group of elements laterally and yieldable relatively to the holder in 15 response to pressure of the shoe on said member.
114. A shoe-pressing device comprising a holder, a shoe-pressing member supported by said holder and flexibly conformable to the contour of 20 a shoe in response to pressure of the shoe thereon, a group of metal balls backing up said shoe-pressing member and arranged to adjust themselves in accordance with the contour of the shoe and then to become substantially fixed relatively to 25 the holder by contact with one another and with the holder, and a row of pins confining said group of balls laterally and mounted in the holder for yielding movements in response to pressure of the shoe on said member.
115. A device for pressing the bottoms of shoes, 30 said device having a metallic shoe-engaging portion conformable to the contour of the bottom of a shoe in response to pressure of the shoe thereon, a holder supporting said shoe-engaging portion, and means also conformable to the contour of the shoe for backing up said shoe-engaging portion, said means being arranged to transmit pressure positively from the holder to said shoe-engaging portion after its conformity to the con- 35 tour of the shoe.
116. A device for pressing the bottoms of shoes, 40 said device comprising a heated resilient shoe-engaging plate arranged to bend and conform itself to the contour of the bottom of a shoe in response to pressure of the shoe thereon, and means also conformable to the contour of the bottom of the shoe for backing up said plate, said means being constructed and arranged to prevent further bending of the plate after its conformity to 45 the bottom of the shoe and thus to increase the pressure of the plate on the shoe.
117. A device for pressing the bottoms of shoes, 50 said device having a heated metallic shoe-engaging portion conformable to the contour of the bottom of a shoe in response to pressure of the shoe thereon, and a group of loose elements backing up said shoe-engaging portion and arranged to adjust themselves in accordance with the contour of the bottom of the shoe and then to support 55 said shoe-engaging portion against the pressure of the shoe upon it.
118. A device for pressing the bottoms of shoes, 60 said device comprising a metal plate flexibly conformable to the contour of the bottom of a shoe in response to pressure of the shoe thereon, a holder supporting said plate, and a group of loose elements backing up said plate and arranged to adjust themselves in accordance with the contour of the bottom of the shoe and then to become substantially fixed relatively to the holder to increase the pressure of the plate on the shoe.
119. A device for pressing the bottoms of shoes, 65 said device comprising a holder, a metal plate in response to pressure of the shoe thereon, a holder supporting said plate, and a group of loose elements backing up said plate and arranged to adjust themselves in accordance with the contour of the bottom of the shoe and then to become substantially fixed relatively to the holder to increase the pressure of the plate on the shoe.

supported by said holder and flexibly conformable to the contour of the bottom of a shoe in response to pressure of the shoe thereon, a group of loose elements backing up said plate and arranged to adjust themselves in accordance with the contour of the shoe and then to become substantially fixed relatively to one another and to the holder by contact with one another and with the holder, and a fence confining said group of elements laterally and yieldable relatively to the holder in response to pressure of the plate thereon.

120. A device for ironing the bottoms of shoes comprising an ironing unit movable inwardly over the bottom of a shoe in wiping contact with the shoe, said unit having a heated shoe-engaging portion conformable to the contour of the bottom of the shoe in response to pressure of the shoe thereon, a holder supporting said shoe-engaging portion, and means also conformable to the contour of the shoe for backing up said shoe-engaging portion, said means being arranged to transmit pressure positively from the holder to said shoe-engaging portion after its conformity to the contour of the shoe.

121. A device for ironing the bottoms of shoes comprising an ironing unit movable inwardly over the bottom of a shoe in wiping contact with the shoe, said unit comprising a resilient shoe-engaging plate flexibly conformable to the contour of the bottom of the shoe in response to pressure of the shoe thereon, a holder supporting said plate, and means also conformable to the contour of the bottom of the shoe arranged to transmit pressure positively from the holder to said plate after the plate has conformed to the shoe bottom.

122. A device for ironing the bottoms of shoes, said device comprising a heated resilient shoe-engaging plate movable inwardly over the bottom of a shoe in wiping contact therewith and flexibly conformable to the contour of the shoe bottom in response to pressure of the shoe thereon, and a group of loose elements backing up said plate and arranged to adjust themselves in accordance with the contour of the shoe and then to support said plate against pressure of the shoe thereon.

123. A device for ironing the bottoms of shoes comprising an ironing unit movable inwardly over the bottom of a shoe in wiping contact with the shoe, said unit comprising a holder, an ironing plate carried by said holder and flexibly conformable to the contour of the shoe in response to pressure of the shoe thereon, and a group of

loose elements backing up said ironing plate and arranged to adjust themselves in accordance with the contour of the shoe and then to become substantially fixed relatively to one another and to the holder to increase the pressure on the shoe.

124. A device for ironing the bottoms of shoes comprising an ironing unit movable inwardly over the bottom of a shoe in wiping contact with the shoe, said unit comprising a holder, an ironing plate carried by said holder and flexibly conformable to the contour of the shoe in response to pressure of the shoe thereon, a group of metal balls backing up said ironing plate and arranged to adjust themselves to the contour of the shoe and then to become substantially fixed relatively to one another and to the holder by contact with one another and with the holder, and a row of members confining said group of balls laterally and yieldable relatively to the holder in response to pressure of the shoe on said plate.

125. A device for pressing the bottoms of shoes, said device comprising heated superposed flexible resilient plates yieldingly conformable to the contour of the bottom of a shoe in response to pressure of the shoe thereon and one of them arranged to engage the bottom of the shoe, said plates having slits therein to increase their flexibility with the slits in each plate arranged in staggered relation to the slits in the adjacent plate.

126. A device for ironing the bottoms of shoes comprising superposed flexible resilient plates movable inwardly over the bottom of a shoe with one of the plates in wiping contact with the shoe, said plates being yieldably conformable to the contour of the shoe bottom and each of them having slits therein extending in substantially parallel relation to the direction of inward movement of the plates with the slits in each plate in staggered relation to the slits in the adjacent plate.

127. A device for pressing the bottoms of shoes, said device comprising a heated metal plate arranged to engage the bottom of a shoe and flexibly conformable to the contour of the bottom of the shoe in response to pressure of the shoe thereon, a holder for said plate, and a group of metal balls in said holder arranged to adjust themselves to the contour of the shoe with said plate and thereafter to increase the pressure of the plate on the shoe.

CERTIFICATE OF CORRECTION.

Patent No. 2,035,468.

March 31, 1936.

SIDNEY J. FINN.

It is hereby certified that error appears in the printed specification of the above numbered patent requiring correction as follows: Page 6, first column, line 17-18, for "depressued" read depressed; page 14, second column, line 65, claim 43, for "shot" read shoe; page 17, second column, line 57, claim 78, after "fluid" insert supplied; page 21, first column, line 3, claim 119, for "shoes" read shoe; and second column, line 37, claim 126, for "yieldably" read yieldingly; and that the said Letters Patent should be read with these corrections therein that the same may conform to the record of the case in the Patent Office.

Signed and sealed this 12th day of May, A. D. 1936.
